LIQUID EJECTION APPARATUS AND PRINT HEAD

The present application is based on, and claims priority from JP Application Serial Number 2022-157664, filed Sep. 30, 2022, the disclosure of which is hereby incorporated by reference herein in its entirety.

BACKGROUND

1. Technical Field

The present disclosure relates to a liquid ejection apparatus and a print head.

2. Related Art

There is a liquid ejection apparatus that ejects a liquid having a configuration including a print head having a piezoelectric element, a pressure chamber, and a nozzle communicating with the pressure chamber. The print head changes a volume of the pressure chamber by driving the piezoelectric element, and ejects a liquid supplied to the pressure chamber from the nozzle. As a configuration of such a liquid ejection apparatus, there is a configuration that realizes ejection control suitable for a temperature of ink by driving and controlling a piezoelectric element based on the temperature of the ink stored in a print head. For example, JP-A-2022-124599 discloses a liquid ejection apparatus in which a temperature detection portion that detects a temperature of a pressure chamber storing ink is provided in a print head having a piezoelectric element, the pressure chamber, and a nozzle, and thus the detection accuracy of a temperature of the pressure chamber can be increased by reducing a temperature difference between a detected temperature and a temperature in the pressure chamber, and a liquid ejection head (print head).

However, in the liquid ejection apparatus disclosed in JP-A-2022-124599, since the temperature detection portion is provided inside the print head, the accuracy of detecting the temperature of the pressure chamber may be reduced, and thus there is room for further improvement.

SUMMARY

According to an aspect of the present disclosure, there is provided a liquid ejection apparatus including a control circuit that outputs a control signal; a first drive signal output circuit that outputs a first drive signal; and a print head that receives the control signal and the first drive signal and ejects a liquid, in which the print head includes a piezoelectric element that includes a first electrode, a second electrode, and a piezoelectric body and in which the piezoelectric body is located between the first electrode and the second electrode in a stacking direction in which the first electrode, the second electrode, and the piezoelectric body are stacked, and that is driven by receiving the first drive signal, a vibration plate that is located on one side of the stacking direction with respect to the piezoelectric element and is deformed by driving the piezoelectric element, a pressure chamber substrate that is located on the one side of the stacking direction with respect to the vibra-

2

tion plate and is provided with a plurality of pressure chambers of which volumes change due to deformation of the vibration plate,

a switch circuit that switches whether or not to supply the first drive signal to the piezoelectric element, a wiring substrate that is provided with the switch circuit, and

a temperature detection portion that is located on the other side of the stacking direction with respect to the vibration plate, is electrically coupled to the wiring substrate, and detects temperature information of the pressure chamber, and

the temperature information detected by the temperature detection portion in a period in which a voltage value of the first drive signal is constant is input to the control circuit.

According to another aspect of the present disclosure, there is provided

a print head that receives a control signal output by a control circuit and a first drive signal output by a first drive signal output circuit and ejects a liquid, including a piezoelectric element that includes a first electrode, a second electrode, and a piezoelectric body and in which the piezoelectric body is located between the first electrode and the second electrode in a stacking direction in which the first electrode, the second electrode, and the piezoelectric body are stacked, and that is driven by receiving the first drive signal,

a vibration plate that is located on one side of the stacking direction with respect to the piezoelectric element and is deformed by driving the piezoelectric element,

a pressure chamber substrate that is located on the one side of the stacking direction with respect to the vibration plate and is provided with a plurality of pressure chambers of which volumes change due to deformation of the vibration plate,

a switch circuit that switches whether or not to supply the first drive signal to the piezoelectric element, a wiring substrate that is provided with the switch circuit, and

a temperature detection portion that is located on the other side of the stacking direction with respect to the vibration plate, is electrically coupled to the wiring substrate, and detects temperature information of the pressure chamber, and

the temperature information detected by the temperature detection portion in a period in which a voltage value of the first drive signal is constant is output.

BRIEF DESCRIPTION OF THE DRAWINGS

FIG. 1 is a diagram illustrating a schematic configuration of a liquid ejection apparatus.

FIG. 2 is a diagram illustrating a functional configuration of the liquid ejection apparatus.

FIG. 3 is a diagram illustrating a configuration of a drive circuit.

FIG. 4 is a diagram illustrating a configuration of a drive signal selection circuit.

FIG. 5 is a diagram for describing a relationship between a latch signal LAT, a change signal CH, a clock signal SCK, a head control signal DI, and a selection signal S.

FIG. 6 is a diagram illustrating an example of a data configuration of the head control signal DI.

FIG. 7 is a diagram illustrating decoding contents of a decoder.

FIG. 8 is a diagram illustrating a configuration of a selection circuit corresponding to a piezoelectric element.

FIG. 9 is a diagram illustrating an example of signal waveforms of drive signals COMA and COMB.

FIG. 10 is a diagram illustrating an example of the head control signal DI.

FIG. 11 is a diagram illustrating a specific example of decoding contents of the decoder.

FIG. 12 is a diagram illustrating a drive signal VOUT output from the selection circuit when selection signals Sa and Sb illustrated in FIG. 11 are supplied.

FIG. 13 is an exploded perspective view illustrating a structure of an ejection module.

FIG. 14 is a plan view of the ejection module.

FIG. 15 is a sectional view taken along the line XV-XV in FIG. 14.

FIG. 16 is a detailed view of a main portion of a configuration in FIG. 15.

FIG. 17 is a sectional view taken along the line XVII-XVII in FIG. 14.

FIG. 18 is a diagram illustrating an example of an acquisition timing of acquiring the temperature of the ejection module.

DESCRIPTION OF EMBODIMENTS

Hereinafter, preferred embodiments of the present disclosure will be described with reference to the drawings. The drawings used are for convenience of description. The embodiments described below do not unreasonably limit the content of the present disclosure described in the claims. Not all of the configurations described below are essential constituent requirements of the present disclosure.

1. Structure of Liquid Ejection Apparatus

FIG. 1 is a diagram illustrating a schematic configuration of a liquid ejection apparatus 1. The liquid ejection apparatus 1 according to the present embodiment will be described by using an example of a serial printing type ink jet printer in which a carriage 21 on which a print head 20 ejecting ink as an example of a liquid is mounted reciprocates along a scanning axis and ejects the ink to a medium P that is transported in a transport direction to form an image on the medium P. As the medium P used in such a liquid ejection apparatus 1, any printing target such as a printing paper, a resin film, or a cloth may be used.

As illustrated in FIG. 1, the liquid ejection apparatus 1 includes an ink container 2, a control mechanism 10, a carriage 21, a movement mechanism 30, and a transport mechanism 40.

A plurality of types of ink to be ejected to the medium P are stored in the ink container 2. Examples of colors of the ink stored in the ink container 2 include black, cyan, magenta, yellow, red, and gray. As the ink container 2 in which such ink is stored, an ink cartridge, a bag-shaped ink pack made of a flexible film, an ink tank capable of replenishing ink, and the like may be used.

The control mechanism 10 includes a processing circuit such as a central processing unit (CPU) or a field programmable gate array (FPGA), and a storage circuit such as a semiconductor memory, and controls each element of the liquid ejection apparatus 1 including the print head 20.

The print head 20 is mounted on the carriage 21, and the carriage 21 is fixed to an endless belt 32 included in the movement mechanism 30. The ink container 2 may be mounted on the carriage 21.

A control signal Ctrl-H for controlling the print head 20 output from the control mechanism 10 and a drive signal

COM for driving the print head 20 are input to the print head 20 mounted on the carriage 21. The ink stored in the ink container 2 is supplied to the print head 20 via a tube (not illustrated). The print head 20 ejects the ink supplied from the ink container 2 based on the input control signal Ctrl-H and drive signal COM.

The movement mechanism 30 includes a carriage motor 31 and the endless belt 32. The carriage motor 31 is operated based on a control signal Ctrl-C input from the control mechanism 10. The endless belt 32 is rotated according to an operation of the carriage motor 31. Consequently, the carriage 21 fixed to the endless belt 32 reciprocates in the scanning axis. That is, the carriage 21 reciprocates along the scanning axis intersecting the transport direction in which the medium P is transported.

The transport mechanism 40 includes a transport motor 41 and a transport roller 42. The transport motor 41 is operated based on a control signal Ctrl-T input from the control mechanism 10. The transport roller 42 is rotated in accordance with the operation of the transport motor 41. The medium P is transported in the transport direction in accordance with the rotation of the transport roller 42.

As described above, the liquid ejection apparatus 1 ejects the ink from the print head 20 mounted on the carriage 21 onto the medium P in conjunction with the transporting of the medium P using the transport mechanism 40 and the reciprocation of the carriage 21 by the movement mechanism 30, and thus the ink is landed at a predetermined position on a surface of the medium P to form a desired image on the medium P.

2. Functional Configuration of Liquid Ejection Apparatus

Next, a functional configuration of the liquid ejection apparatus 1 will be described. FIG. 2 is a diagram illustrating a functional configuration of the liquid ejection apparatus 1. As illustrated in FIG. 2, the liquid ejection apparatus 1 includes the control mechanism 10, the print head 20, the carriage motor 31, the transport motor 41, and a linear encoder 90.

The control mechanism 10 includes drive circuits 50a and 50b, a reference voltage signal output circuit 52, and a control circuit 100. For example, the control circuit 100 includes a processing circuit such as a CPU and an FPGA and a storage circuit such as a semiconductor memory. An image information signal including image data or the like is input to the control circuit 100 from an external apparatus such as a host computer that is communicatively connected to the outside of the liquid ejection apparatus 1. The control circuit 100 generates various signals for controlling the liquid ejection apparatus 1 based on the input image information signal, and outputs the various signals to corresponding configurations.

As a specific example, in addition to the image information signal described above, a detection signal based on a scanning position of the carriage 21 is input from the linear encoder 90 to the control circuit 100. The control circuit 100 ascertains a scanning position of the print head 20 mounted on the carriage 21 based on the input detection signal. The control circuit 100 generates and outputs various signals according to the scanning position of the print head 20 and the image information signal.

Specifically, the control circuit 100 generates the control signal Ctrl-C for controlling movement of the print head 20 along the scanning axis according to the scanning position of the print head 20, and outputs the control signal Ctrl-C to the carriage motor 31. As a result, the carriage motor 31 is operated, and movement of the print head 20 mounted on the carriage 21 along the scanning axis and a scanning position

thereof are controlled. The control circuit 100 generates the control signal Ctrl-T for controlling transport of the medium P, and outputs the control signal Ctrl-T to the transport motor 41. As a result, the transport motor 41 is operated, and movement of the medium P in the transport direction is controlled. The control signal Ctrl-C may be input to the carriage motor 31 after being signal-converted via a driver circuit (not illustrated). Similarly, the control signal Ctrl-T may be input to the transport motor 41 after being signal-converted via a driver circuit (not illustrated).

The control circuit 100 generates head control signals DI1 to DI_n, a change signal CH, a latch signal LAT, and a clock signal SCK as the control signals Ctrl-H for controlling the print head 20 based on the image information signal input from the external apparatus and the scanning position of the print head 20 input from the linear encoder 90, and outputs these signals to the print head 20.

The control circuit 100 generates a temperature acquisition request signal TD for acquiring the temperature of the print head 20 at a predetermined timing, and outputs the temperature acquisition request signal TD to the print head 20. A temperature information signal TI output by the print head 20 is input to the control circuit 100 in response to the temperature acquisition request signal TD. That is, the temperature information signal TI including information regarding the temperature of the print head 20 is input to the control circuit 100. The control circuit 100 corrects the control signals Ctrl-H, Ctrl-C, and Ctrl-T based on the input temperature information signal TI.

The control circuit 100 outputs a basic drive signal dA, which is a digital signal, to the drive circuit 50a. The drive circuit 50a performs digital/analog conversion of the input basic drive signal dA, then amplifies the converted analog signal in class D to generate the drive signal COMA, and outputs the drive signal COMA to the print head 20. The control circuit 100 outputs a basic drive signal dB, which is a digital signal, to the drive circuit 50b. The drive circuit 50b performs digital/analog conversion of the input basic drive signal dB, then amplifies the converted analog signal in class D to generate the drive signal COMB, and outputs the drive signal COMB to the print head 20.

That is, the basic drive signals dA and dB output by the control circuit 100 are digital signals that define waveforms of the drive signals COMA and COMB. The basic drive signals dA and dB may be any signals that can define waveforms of the drive signals COMA and COMB output by the drive circuits 50a and 50b, and may be analog signals, for example. Here, the drive circuits 50a and 50b all have the same configuration, and may be referred to as a drive circuit 50 when it is not necessary to distinguish the drive circuits. In this case, a description will be made assuming that a digital basic drive signal dO is input to the drive circuit 50 and the drive signal COM is output. The details of the drive circuit 50 will be described later.

The reference voltage signal output circuit 52 generates a reference voltage signal VBS and outputs the reference voltage signal VBS to the print head 20. The reference voltage signal VBS output by the reference voltage signal output circuit 52 may be a signal having a potential that is a reference for driving a piezoelectric element 60 that will be described later, and may be, for example, a signal constant at the ground potential, and may be a constant DC voltage signal at a potential of 5.5 V, 6 V, or the like. The reference voltage signal output circuit 52 may be integrally configured with the drive circuit 50.

The print head 20 includes ejection modules 22-1 to 22-n and a temperature information output circuit 26. Each of the

ejection modules 22-1 to 22-n includes a drive signal selection circuit 200, a temperature detection circuit 24, and piezoelectric elements 60[1] to 60[m].

The head control signal DI1, the change signal CH, the latch signal LAT, and the clock signal SCK output by the control circuit 100, the drive signals COMA and COMB output by the drive circuits 50a and 50b, and the reference voltage signal VBS output by the reference voltage signal output circuit 52 are input to the ejection module 22-1.

10 The clock signal SCK, the latch signal LAT, the change signal CH, the head control signal DI1, and the drive signals COMA and COMB input to the ejection module 22-1 are input to the drive signal selection circuit 200. The drive signal selection circuit 200 selects or does not select signal waveforms of the drive signals COMA and COMB based on the input clock signal SCK, latch signal LAT, change signal CH, and head control signal DI1, and thus generates drive signals VOUT[1] to VOUT[m]. The drive signal selection circuit 200 individually outputs the generated drive signals 15 VOUT[1] to VOUT[m] to first ends of the corresponding piezoelectric elements 60[1] to 60[m]. The reference voltage signal VBS is commonly input to second ends of the piezoelectric elements 60[1] to 60[m]. The piezoelectric elements 60[1] to 60[m] are driven according to potential differences between the drive signals VOUT[1] to VOUT 20 [m] individually input to the first ends and the reference voltage signal VBS commonly input to the second ends. An amount of ink corresponding to driving of each of the piezoelectric elements 60[1] to 60[m] is ejected from the 25 ejection module 22-1.

30 Here, in the print head 20 of the present embodiment, a description will be made assuming that the drive signal VOUT[1] corresponds to the piezoelectric element 60[1], and the drive signal VOUT[m] corresponds to the piezoelectric element 60[m]. That is, the description will be made assuming that the drive signal VOUT[1] generated by the drive signal selection circuit 200 is input to the first end of the piezoelectric element 60[1], and the drive signal VOUT [m] generated by the drive signal selection circuit 200 is 35 input to the first end of the piezoelectric element 60[m].

40 The piezoelectric elements 60[1] to 60[m] all have the same configuration, and may be referred to as a piezoelectric element 60 when it is not necessary to distinguish the piezoelectric elements. In this case, a description will be 45 made assuming that the drive signal VOUT is supplied as the drive signals VOUT[1] to VOUT[m] to the first end of the piezoelectric element 60. That is, the description will be made assuming that the piezoelectric element 60 is driven according to a potential difference between the drive signal VOUT supplied to the first end and the reference voltage signal VBS supplied to a second end.

50 The temperature detection circuit 24 included in the ejection module 22-1 detects the temperature of the ejection module 22-1. The temperature detection circuit 24 outputs 55 the detected temperature of the ejection module 22-1 to the temperature information output circuit 26 as temperature detection information TH1.

56 Here, the ejection module 22-2 to the ejection module 22-n have the same configuration as the ejection module 22-1 except that the input signals and the output signals are different, and perform the same operation.

57 That is, the clock signal SCK, the latch signal LAT, the change signal CH, the head control signal DI, the drive signals COMA and COMB, and the reference voltage signal 60 VBS are input to the ejection module 22-n. The drive signal selection circuit 200 included in the ejection module 22-n selects or does not select signal waveforms of the drive

signals COMA and COMB based on the input clock signal SCK, latch signal LAT, change signal CH, and head control signal DI, to generate drive signals VOUT[1] to VOUT[m]. The drive signals VOUT[1] to VOUT[m] generated by the drive signal selection circuit 200 included in the ejection module 22-n are input to the first ends of the corresponding piezoelectric elements 60[1] to 60[m] included in the ejection module 22-n. A reference voltage signal VBS is commonly input to second ends of the piezoelectric elements 60[1] to 60[m] included in the ejection module 22-n. As a result, the piezoelectric elements 60[1] to 60[m] of the ejection module 22-n are driven, and an amount of ink corresponding to driving of the piezoelectric elements 60[1] to 60[m] is ejected from the ejection module 22-n. The temperature detection circuit 24 included in the ejection module 22-n detects the temperature of the ejection module 22-n and outputs the detected temperature as temperature detection information TH.

Therefore, in the following description, when it is not necessary to distinguish the ejection modules 22-1 to 22-n, the ejection modules may be simply referred to as an ejection module 22. In this case, a description will be made assuming that the clock signal SCK, the latch signal LAT, the change signal CH, the head control signal DI, the drive signals COMA and COMB, and the reference voltage signal VBS are input to the ejection module 22, and the temperature detection information TH indicating the temperature of the ejection module 22 is output.

The pieces of temperature detection information TH1 to THn output by the temperature detection circuits 24 included in each of the ejection modules 22-1 to 22-n and the temperature acquisition request signal TD output by the control circuit 100 are input to the temperature information output circuit 26. The temperature information output circuit 26 amplifies and stores each of the pieces of temperature detection information TH1 to THn. The temperature information output circuit 26 outputs, as the temperature information signal TI, a corresponding signal among signals obtained by amplifying each of the pieces of temperature detection information TH1 to THn stored in accordance with the temperature acquisition request signal TD input from the control circuit 100. Such a temperature information output circuit 26 includes an amplification circuit that amplifies the pieces of temperature detection information TH1 to THn, a processor such as a microcomputer that receives the input temperature acquisition request signal TD and outputs the temperature information signal TI obtained by amplifying the temperature detection information TH1 to THn, and a storage circuit that amplifies and stores each of the pieces of temperature detection information TH1 to THn.

The temperature information output circuit 26 may store each of the pieces of temperature detection information TH1 to THn output by the temperature detection circuits 24 included in the respective ejection modules 22-1 to 22-n, amplify each of the stored pieces of temperature detection information TH1 to THn according to the temperature acquisition request signal TD input from the control circuit 100, and output the amplified signal as the temperature information signal TI.

As described above, the liquid ejection apparatus 1 of the present embodiment includes the drive circuits 50a and 50b that output the drive signals COMA and COMB, and the print head 20 that receives the control signal Ctrl-H including the clock signal SCK, the latch signal LAT, the change signal CH, and the head control signal DI, which are output by the control circuit 100, and the drive signal COM, and ejects the ink. In other words, the print head 20 receives the

clock signal SCK, the latch signal LAT, the change signal CH, and the head control signal DI output by the control circuit 100, and the drive signals COMA and COMB output by the drive circuit 50, and ejects ink.

5. Configuration of Drive Circuit

Next, a configuration and an operation of the drive circuit 50 that outputs the drive signal COM will be described. FIG. 3 is a diagram illustrating a configuration of the drive circuit 50. The drive circuit 50 includes an integrated circuit 500, an amplification circuit 550, a demodulation circuit 560, feedback circuits 570 and 572, and other electronic components.

The integrated circuit 500 has a plurality of terminals including a terminal In, a terminal Bst, a terminal Hdr, a terminal Sw, a terminal Gvd, a terminal Ldr, a terminal Gnd, a terminal Vfb, and a terminal Ifb. The integrated circuit 500 is electrically coupled to an externally provided substrate (not illustrated) via the plurality of terminals. The integrated circuit 500 includes a digital to analog converter (DAC) 511, a modulation circuit 510, and a gate drive circuit 520.

The DAC 511 converts the input basic drive signal dO of a digital signal into a basic drive signal aO of an analog signal, and outputs the basic drive signal aO to the modulation circuit 510. A signal obtained by amplifying the basic drive signal aO output by the DAC 511 corresponds to the drive signal COM. That is, the basic drive signal aO corresponds to a target signal before amplification of the drive signal COM, and the basic drive signals dO and aO are signals defining a signal waveform of the drive signal COM.

The modulation circuit 510 generates a modulation signal Ms obtained by modulating the basic drive signal aO and outputs the modulation signal Ms to the gate drive circuit 520. The modulation circuit 510 includes adders 512 and 513, a comparator 514, an inverter 515, an integration attenuator 516, and an attenuator 517.

The integration attenuator 516 attenuates and integrates the drive signal COM input via the terminal Vfb and outputs the drive signal COM to an input terminal on the negative side of the adder 512. The basic drive signal aO is input to an input terminal on the positive side of the adder 512. The adder 512 outputs a voltage obtained by subtracting and integrating a voltage input to the input terminal on the negative side from a voltage input to the input terminal on the positive side to an input terminal on the positive side of the adder 513.

The attenuator 517 outputs a voltage obtained by attenuating a high frequency component of the drive signal COM input via the terminal Ifb to the input terminal on the negative side of the adder 513. The voltage output from the adder 512 is input to the input terminal on the positive side of the adder 513. The adder 513 generates a voltage signal Os obtained by subtracting the voltage input to the input terminal on the negative side from the voltage input to the input terminal on the positive side, and outputs the voltage signal Os to the comparator 514.

The comparator 514 outputs the modulation signal Ms obtained by pulse-modulating the voltage signal Os input from the adder 513. Specifically, the comparator 514 generates and outputs the modulation signal Ms that has an H level when a voltage value of the voltage signal Os input from the adder 513 is a predetermined threshold value Vth1 or greater in a case where the voltage value increases, and that has an L level when the voltage value of the voltage signal Os is smaller than a predetermined threshold value Vth2 in a case where the voltage value decreases. Here, for the threshold values Vth1 and Vth2, the threshold value Vth1 is the threshold value Vth2.

The modulation signal Ms output by the comparator 514 is input to a gate driver 521 included in the gate drive circuit 520, and is also input to a gate driver 522 included in the gate drive circuit 520 via the inverter 515. That is, signals having a relationship in which the logic levels are exclusive are input to the gate driver 521 and the gate driver 522. Here, the relationship in which the logic levels are exclusive includes that the logic levels of the signals input to the gate driver 521 and the gate driver 522 are not simultaneously in an H level. Therefore, the modulation circuit 510 may include a timing control circuit controlling timings of the modulation signal Ms input to the gate driver 521 and the signal in which the logic level of the modulation signal Ms input to the gate driver 522 is inverted, instead of or in addition to the inverter 515.

The gate drive circuit 520 includes the gate driver 521 and the gate driver 522. The gate driver 521 level-shifts the modulation signal Ms output from the comparator 514 to generate an amplification control signal Hgd, and outputs the amplification control signal Hgd from the terminal Hdr.

Specifically, within a power supply voltage for the gate driver 521, a voltage is supplied to the high level side via the terminal Bst, and a voltage is supplied to the low level side via the terminal Sw. The terminal Bst is coupled to a first end of a capacitor C5 and a cathode of a diode D1 for preventing backflow. The terminal Sw is coupled to a second end of the capacitor C5. An anode of the diode D1 is coupled to the terminal Gvd. A voltage signal Vm, which is a DC voltage of, for example, 7.5 V, output by a power supply circuit (not illustrated) is supplied to the terminal Gvd. That is, the voltage signal Vm is supplied to the anode of the diode D1. Therefore, a potential difference between the terminal Bst and the terminal Sw is approximately equal to a voltage value of the voltage signal Vm. As a result, the gate driver 521 generates the amplification control signal Hgd having a voltage value greater than that of the terminal Sw by the voltage signal Vm according to the input modulation signal Ms, and outputs the amplification control signal Hgd from the terminal Hdr.

The gate driver 522 is operated on the lower potential side than the gate driver 521. The gate driver 522 level-shifts the signal in which the logic level of the modulation signal Ms output from the comparator 514 is inverted by the inverter 515 to generate an amplification control signal, and outputs the amplification control signal Lgd from the terminal Ldr.

Specifically, within a power supply voltages for the gate driver 522, the voltage signal Vm is supplied to the high level side, and a ground potential is supplied to the low level side via the terminal Gnd. The gate driver 522 outputs, from the terminal Ldr, the amplification control signal Lgd having a voltage value greater than that of the terminal Gnd by the voltage signal Vm according to the signal in which the logic level of the input modulation signal Ms is inverted. Here, the ground potential is a reference potential of the drive circuit 50, and is, for example, 0 V.

The amplification circuit 550 includes a transistor M1 and a transistor M2.

The transistor M1 is a surface mount-type field effect transistor (FET), and a voltage signal VHV, which is a DC voltage of, for example, 42 V, is supplied to a drain of the transistor M1 as a power supply voltage for amplification of the amplification circuit 550. A gate of the transistor M1 is electrically coupled to a first end of a resistor R1 and a second end of the resistor R1 is electrically coupled to the terminal Hdr of the integrated circuit 500. That is, the amplification control signal Hgd is input to the gate of the

transistor M1. A source of the transistor M1 is electrically coupled to the terminal Sw of the integrated circuit 500.

The transistor M2 is a surface mount-type FET, and a drain of the transistor M2 is electrically coupled to the terminal Sw of the integrated circuit 500. That is, the drain of the transistor M2 and the source of the transistor M1 are electrically coupled to each other. A gate of the transistor M2 is electrically coupled to a first end of a resistor R2, and a second end of the resistor R2 is electrically coupled to the terminal Ldr of the integrated circuit 500. That is, the amplification control signal Lgd is input to the gate of the transistor M2. A ground potential is supplied to a source of the transistor M2.

On the other hand, when the drain and the source of the transistor M1 are controlled to be conductive and the drain and the source of the transistor M2 are controlled to be non-conductive, a potential of a node coupled to the terminal Sw becomes the ground potential. Therefore, the voltage signal Vm is supplied to the terminal Bst. On the other hand, when the drain and the source of the transistor M1 are controlled to be conductive and the drain and the source of the transistor M2 are controlled to be non-conductive, the potential of the node coupled to which the terminal Sw has a voltage value of the voltage signal VHV. Therefore, a voltage corresponding to a potential of a sum of the voltage value of the voltage signal VHV and the voltage value of the voltage signal Vm is supplied to the terminal Bst. That is, the gate driver 521 that drives the transistor M1 generates the amplification control signal Hgd of which an L level is a voltage value of the voltage signal VHV and an H level is a voltage value corresponding to a sum of the voltage value of a voltage signal VHV and a voltage value of the voltage signal Vm when a potential of the terminal Sw is changed to the ground potential or the voltage signal VHV according to operations of the transistor M1 and the transistor M2 with the capacitor C5 as a floating power supply, and outputs the amplification control signal Hgd to the gate of the transistor M1.

On the other hand, the gate driver 522 that drives the transistor M2 generates an amplification control signal Lgd of which an L level is the ground potential and an H level is the voltage value of the voltage signal Vm, regardless of operations of the transistor M1 and the transistor M2 and outputs the amplification control signal Lgd to the gate of the transistor M2.

The amplification circuit 550 configured as described above generates an amplification modulation signal AMs obtained by amplifying the modulation signal Ms based on the voltage signal VHV at a coupling point between the source of the transistor M1 and the drain of the transistor M2. The amplification circuit 550 outputs the generated amplification modulation signal AMs to the demodulation circuit 560.

Here, a capacitor C7 is provided in a propagation path through which the voltage signal VHV input to the amplification circuit 550 propagates. Specifically, a first end of the capacitor C7 is electrically coupled to the drain of the transistor M1 on the propagation path through which the voltage signal VHV propagates, and, the ground potential is supplied to a second end of the capacitor C7. Consequently, a probability that a voltage value of the voltage signal VHV input to the amplification circuit 550 varies is reduced, a probability that noise is superimposed on the voltage signal VHV is reduced, and as a result, the waveform accuracy of the amplification modulation signals AMs output by the amplification circuit 550 is improved. Thus, an electrolytic capacitor having a high breakdown voltage and a large

11

capacity is used. The capacitor C7 may be provided to correspond to one drive circuit 50, or may be provided to correspond to a plurality of drive circuits 50.

The demodulation circuit 560 generates the drive signal COM by demodulating the amplification modulation signal AMs output by the amplification circuit 550, and outputs the drive signal COM from the drive circuit 50. The demodulation circuit 560 includes an inductor L1 and a capacitor C1. A first end of the inductor L1 is coupled to a first end of the capacitor C1. The amplification modulation signal AMs is input to a second end of the inductor L1. The ground potential is supplied to a second end of the capacitor C1. That is, in the demodulation circuit 560, the inductor L1 and the capacitor C1 form a low-pass filter. The demodulation circuit 560 demodulates the amplification modulation signal AMs by smoothing the amplification modulation signal AMs with the low-pass filter, and outputs the demodulated signal as the drive signal COM. That is, the drive circuit 50 outputs the drive signal COM from the first end of the inductor L1 included in the demodulation circuit 560 and the first end of the capacitor C1.

The feedback circuit 570 includes a resistor R3 and a resistor R4. The drive signal COM is supplied to a first end of the resistor R3, and a second end thereof is coupled to the terminal Vfb and a first end of the resistor R4. The voltage signal VHV is supplied to a second end of the resistor R4. Consequently, the drive signal COM that has passed through the feedback circuit 570 is fed back to the terminal Vfb in a state of being pulled up by the voltage value of the voltage signal VHV.

The feedback circuit 572 includes capacitors C2, C3, and C4 and resistors R5 and R6. The drive signal COM is input to a first end of the capacitor C2, and a second end thereof is coupled to a first end of the resistor R5 and a first end of the resistor R6. The ground potential is supplied to a second end of the resistor R5. Consequently, the capacitor C2 and the resistor R5 function as a high-pass filter. A second end of the resistor R6 is coupled to the first end of the capacitor C4 and the first end of the capacitor C3. The ground potential is supplied to a second end of the capacitor C3. Consequently, the resistor R6 and the capacitor C3 function as a low-pass filter. That is, the feedback circuit 572 includes a high-pass filter and a low-pass filter, and functions as a band-pass filter through which a signal in a predetermined frequency range included in the drive signal COM passes.

A second end of the capacitor C4 is coupled to the terminal Ifb of the integrated circuit 500. As a result, among high frequency components of the drive signal COM that has passed through the feedback circuit 572 that functions as a band-pass filter, a signal of which a DC component is cut is fed back to the terminal Ifb.

The drive signal COM is a signal obtained by the demodulation circuit 560 smoothing the amplification modulation signal AMs based on the basic drive signal do. The drive signal COM is integrated and subtracted via the terminal Vfb, and then fed back to the adder 512. As a result, the drive circuit 50 self-oscillates at a frequency determined by a feedback delay and a feedback transfer function. However, the feedback path via the terminal Vfb has a large delay amount. Therefore, it may not be possible to increase a frequency of self-oscillation to such an extent that the accuracy of the drive signal COM can be sufficiently ensured only by feedback via the terminal Vfb. Therefore, by providing a path for feeding back the high frequency component of the drive signal COM via the terminal Ifb separately from the path via the terminal Vfb, the delay in the entire circuit is reduced. As a result, a frequency of the voltage

12

signal Os can be increased to such an extent that the accuracy of the drive signal COM can be sufficiently ensured compared with the case where the path via the terminal Ifb does not exist.

As described above, the drive circuit 50 generates the drive signal COM by performing digital/analog conversion of the input basic drive signal dO and then amplifying the analog signal in class D, and outputs the generated drive signal COM. That is, the drive circuit 50 includes a class-D 10 amplification circuit, and the print head 20 receives the drive signal COM output by the drive circuit 50 including the class-D amplification circuit and ejects a liquid.

4. Configuration of Drive Signal Selection Circuit

Next, a configuration and an operation of the drive signal 15 selection circuit 200 will be described. As described above, the drive signal selection circuit 200 generates the drive signal VOUT by selecting or not selecting signal waveforms of the drive signals COMA and COMB, and outputs the drive signal VOUT to the first end of the piezoelectric element 60.

FIG. 4 is a diagram illustrating a configuration of the drive signal selection circuit 200. As illustrated in FIG. 4, the drive signal selection circuit 200 includes a selection control circuit 210 and selection circuits 230[1] to 230[m] respectively corresponding to the piezoelectric elements 60[1] to 60[m].

The clock signal SCK, the latch signal LAT, the change signal CH, and the head control signal DI are input to the selection control circuit 210. The selection control circuit 30 210 generates selection signals Sa[1] to Sa[m] and Sb[1] to Sb[m] for switching whether to output signal waveforms included in the drive signals COMA and COMB as the drive signal VOUT based on the input clock signal SCK, latch signal LAT, change signal CH, and head control signal DI. 35 The selection signals Sa[1] to Sa[m] and Sb[1] to Sb[m] generated by the selection control circuit 210 are input to the corresponding selection circuits 230[1] to 230[m]. The selection circuits 230[1] to 230[m] select or do not select signal waveforms of the drive signals COMA and COMB based on the input selection signals Sa[1] to Sa[m] and Sb[1] to Sb[m] to generate drive signals VOUT[1] to VOUT[m] corresponding to piezoelectric elements 60[1] to 60[m], and output the drive signals VOUT[1] to VOUT[m] to the corresponding piezoelectric elements 60[1] to 60[m]. Here, 40 the selection circuits 230[1] to 230[m] all have the same configuration, and the selection circuits 230[1] to 230[m] corresponding to the piezoelectric element 60 among the piezoelectric elements 60[1] to 60[m] will be referred to as a selection circuit 230. In this case, the description will be made assuming that the selection circuit 230 selects or does not select the signal waveforms of the drive signals COMA and COMB based on the selection signals Sa and Sb among the selection signals Sa[1] to Sa[m] and Sb[1] to Sb[m].

In describing the details of the operation of the selection 55 control circuit 210, outlines of the latch signal LAT, the change signal CH, the clock signal SCK, and the head control signal DI input to the selection control circuit 210 will be described. FIG. 5 is a diagram for describing a relationship between the latch signal LAT, the change signal 60 CH, the clock signal SCK, the head control signal DI, and the selection signal S.

The latch signal LAT is a pulse signal based on a signal output by the linear encoder 90 indicating a scanning position of the print head 20 and defines a cycle tp in which the print head 20 forms dots on the medium P. The change signal CH is a pulse signal that defines a switching timing of whether or not to supply the signal waveforms included in

the drive signals COMA and COMB to the piezoelectric element 60, and divides the cycle tp into periods t1 and t2. The drive signal selection circuit 200 selects or does not select the signal waveform included in the drive signals COMA and COMB in each of the periods t1 and t2 in which the cycle tp defined by the latch signal LAT is divided by the change signal CH, to generate the drive signal VOUT, and outputs the drive signal VOUT to the piezoelectric element 60.

The head control signal DI serially includes an ejection control signal SI and a waveform selection signal SP. The ejection control signal SI individually defines an ejection amount of the ink ejected by driving the piezoelectric element 60 for each of the piezoelectric elements 60[1] to 60[m]. The waveform selection signal SP defines a relationship between logic levels of the selection signals Sa and Sb output in each of the periods t1 and t2 and the ejection control signal SI.

As illustrated in FIG. 5, the head control signal DI is input to the selection control circuit 210 in synchronization with the clock signal SCK in the cycle tp before the latch signal LAT rises. In this case, the head control signal DI input to the selection control circuit 210 is stored in a register corresponding to each of the piezoelectric elements 60[1] to 60[m]. The head control signal DI stored in the register is latched all at once at a rising edge of the latch signal LAT. That is, at the timing of the start of the cycle tp, the head control signal DI stored in the register is latched all at once. The selection control circuit 210 generates the selection signals Sa and Sb corresponding to each of the periods t1 and t2 in the cycle tp after the latch signal LAT rises, based on the head control signal DI latched all at once, and outputs the selection signals Sa and Sb to the selection circuit 230.

Here, details of the head control signal DI including the ejection control signal SI and the waveform selection signal SP will be described. FIG. 6 is a diagram illustrating an example of a data configuration of the head control signal DI. As illustrated in FIG. 6, the head control signal DI includes the ejection control signal SI and the waveform selection signal SP.

The ejection control signal SI is a signal that defines an ejection amount of the ink ejected by driving the piezoelectric element 60, and includes upper ejection data SIH and lower ejection data SIL. That is, the ejection control signal SI includes 2-bit data of the upper ejection data SIH and the lower ejection data SIL for controlling driving of the piezoelectric element 60 to correspond to each of the piezoelectric elements 60[1] to 60[m].

Specifically, the ejection control signal SI serially includes m-bit upper ejection data SIH corresponding to each of the piezoelectric elements 60[1] to 60[m] in an order of the upper ejection data SIH corresponding to the piezoelectric element 60[m], the upper ejection data SIH corresponding to the piezoelectric element 60[m-1], . . . , the upper ejection data SIH corresponding to the piezoelectric element 60[1], and serially includes, following the upper ejection data SIH, m-bit lower ejection data SIL corresponding to each of the piezoelectric elements 60[1] to 60[m] in an order of the lower ejection data SIL corresponding to the piezoelectric element 60[m], the lower ejection data SIL corresponding to the piezoelectric element 60[m-1], . . . , the lower ejection data SIL corresponding to the piezoelectric element 60[1]. That is, the ejection control signal SI is a 2 m-bit signal serially including m-bit upper ejection data SIH corresponding to the piezoelectric elements 60[m] to 60[1] and m-bit lower ejection data SIL corresponding to the piezoelectric elements 60[m] to 60[1]. The ejection amount

of the ink ejected by driving the piezoelectric element 60[i], i being any one of 1 to m, is defined by 2 bits of the upper ejection data SIH corresponding to the piezoelectric element 60[i] and the piezoelectric element 60[i] corresponding to the lower ejection data SIL.

Here, in the following description, in some cases, the upper ejection data SIH corresponding to the piezoelectric element 60[i] will be referred to as upper ejection data SIHi, and the lower ejection data SIL corresponding to the piezoelectric element 60[i] will be referred to as lower ejection data SILi. Here, in the following description, in some cases, the upper ejection data SIH and the lower ejection data SIL corresponding to the piezoelectric element 60 will be collectively referred to as ejection data [SIH, SIL], and the upper ejection data SIHi and the lower ejection data SILi corresponding to the piezoelectric element 60[i] will be collectively referred to as ejection data [SIHi, SILi]. That is, the ejection amount of the ink ejected by driving the piezoelectric element 60[i] is defined by the ejection data [SIHi, SILi].

The waveform selection signal SP is a signal that defines a drive pattern of the piezoelectric element 60 corresponding to the ejection data [SIH, SIL] in each of the periods t1 and t2, and defines logic levels of the selection signals Sa and Sb output in each of t1 and t2 corresponding to the ejection data [SIH, SIL]. The waveform selection signal SP in the present embodiment is a 16-bit signal including setting information SP00 to SP03, SP10 to SP13, SP20 to SP23, and SP30 to SP33.

Specifically, the waveform selection signal SP serially includes the setting information SP00 to SP03 defining a drive pattern of the piezoelectric element 60 based on the selection signal Sa in the period t1 determined by the ejection data [SIH, SIL], the setting information SP10 to SP13 defining a drive pattern of the piezoelectric element 60 based on the selection signal Sa in the period t2 determined by the ejection data [SIH, SIL], the setting information SP20 to SP23 defining a drive pattern of the piezoelectric element 60 based on the selection signal Sb in the period t1 determined by the ejection data [SIH, SIL], and the setting information SP30 to SP33 defining a drive pattern of the piezoelectric element 60 based on the selection signal Sb in the period t2 determined by the ejection data [SIH, SIL] in an order of the setting information SP33, SP32, SP31, SP30, SP23, SP22, SP21, SP20, SP13, SP12, SP11, SP10, SP03, SP02, SP01, and SP00. The waveform selection signal SP is not limited to a 16-bit signal, but may be a signal of 16 bits or more or a signal of 16 bits or less according to the number of periods into which the cycle tp is divided by the change signal CH or the number of drive patterns of the piezoelectric element 60 defined by the ejection control signal SI.

Returning to FIG. 4, the selection control circuit 210 includes a control logic circuit 260 and selection signal output portions 270[1] to 270[m] provided to correspond to the piezoelectric elements 60[1] to 60[m]. The selection control circuit 210 generates the selection signals Sa[1] to Sa[m] and Sb[1] to Sb[m] respectively corresponding to the piezoelectric elements 60[1] to 60[m] and outputs the selection signals to the corresponding selection circuits 230[1] to 230[m], based on the head control signal DI propagating in synchronization with the clock signal SCK at a timing defined by the input latch signal LAT and change signal CH.

The control logic circuit 260 includes an SP register group 261 and a selection control signal generation portion 262. The SP register group 261 includes a plurality of serially coupled registers, and configures a so-called shift register that causes the head control signal DI that is input in

synchronization with the clock signal SCK to sequentially propagate to the subsequent registers. When the supply of the clock signal SCK is stopped, the SP register group 261 stores the setting information SP00 to SP33 included in the waveform selection signal SP of the head control signal DI.

The selection control signal generation portion 262 latches the setting information SP00 to SP33 stored in the SP register group 261 at the rising edge of the latch signal LAT. The selection control signal generation portion 262 generates selection control signals Q0, Q1, Q2, and Q3 by translating the latched setting information SP00 to SP33, and outputs the selection control signals Q0, Q1, Q2, and Q3 to a decoder 226 of each of the selection signal output portions 270[1] to 270[m]. The selection control signal Q0 includes the setting information SP00, SP01, SP02, and SP03, and defines a logic level of the selection signal Sa output from the selection control circuit 210 in the period t1. The selection control signal Q1 includes the setting information SP10, SP11, SP12, and SP13, and defines a logic level of the selection signal Sa output from the selection control circuit 210 in the period t2. The selection control signal Q2 includes the setting information SP20, SP21, SP22, and SP23, and defines a logic level of the selection signal Sb output from the selection control circuit 210 in the period t1. The selection control signal Q3 includes the setting information SP30, SP31, SP32, and SP33, and defines a logic level of the selection signal Sb output from the selection control circuit 210 in the period t2. Here, in the following description, in some cases, the selection control signal Q0 including the setting information SP00, SP01, SP02, SP03 will be referred to as a selection control signal Q0[SP00, SP01, SP02, SP03], the selection control signal Q1 including the setting information SP10, SP11, SP12, SP13 will be referred to as a selection control signal Q1[SP10, SP11, SP12, SP13], the selection control signal Q2 including the setting information SP20, SP21, SP22, SP23 will be referred to as a selection control signal Q2[SP20, SP21, SP22, SP23], and the selection control signal Q3 including the setting information SP30, SP31, SP32, SP33 will be referred to as a selection control signal Q3[SP30, SP31, SP32, SP33].

Each of the selection signal output portions 270[1] to 270[m] has a first register 222a, a second register 222b, a first latch circuit 224a, a second latch circuit 224b, and a decoder 226.

The second register 222b included in each of the selection signal output portions 270[1] to 270[m] is serially coupled to the subsequent stage of the SP register group 261 including a plurality of registers, and the first register 222a included in each of the selection signal output portions 270[1] to 270[m] is serially coupled to the subsequent stage of the m second registers 222b coupled serially.

Specifically, the second register 222b included in the selection signal output portion 270[1] is coupled to the subsequent stage of the SP register group 261, and the second register 222b included in the selection signal output portion 270[2], the second register 222b included in the selection signal output portion 270[3], . . . , and the second register 222b included in the selection signal output portion 270[m] are coupled serially in order to the subsequent stage of the second register 222b included in the selection signal output portion 270[1]. The first register 222a included in the selection signal output portion 270[1] is coupled to the subsequent stage of the second register 222b included in the selection signal output portion 270[m]. The first register 222a included in the selection signal output portion 270[2], the first register 222a included in the selection signal output

portion 270[3], . . . , and the first registers 222a included in the selection signal output portion 270[m] are coupled serially in order to the subsequent stage of the first register 222a included in the selection signal output portion 270[1].

In other words, the SP register group 261, the m second registers 222b respectively included in the selection signal output portions 270[1] to 270[m], and the m first registers 222a respectively included in the selection signal output portions 270[1] to 270[m] configure a shift register. The head control signal DI input to the SP register group 261 propagates to the subsequent stage in the order of the m second registers 222b respectively included in the selection signal output portions 270[1] to 270[m] and the m first registers 222a respectively included in the selection signal output portions 270[1] to 270[m] in synchronization with the clock signal SCK. Thereafter, when the supply of the clock signal SCK is stopped, the lower ejection data SILi corresponding to the piezoelectric element 60[i] is stored in the second register 222b included in the selection signal output portion 270[i], and the upper ejection data SIHi corresponding to the piezoelectric element 60[i] is stored in the first register 222a included in the selection signal output portion 270[i].

The upper ejection data SIH stored in the first register 222a included in each of the selection signal output portions 270[1] to 270[m] is latched by the corresponding first latch circuit 224a at the rising edge of the latch signal LAT, and the lower ejection data SIL stored in the second register 222b included in each of the selection signal output portions 270[1] to 270[m] is latched by the corresponding second latch circuit 224b at the rising edge of the latch signal LAT. The first latch circuit 224a outputs the latched upper ejection data SIH to the decoder 226 as latch data LTa, and the second latch circuit 224b outputs the latched lower ejection data SIL to the decoder 226 as latch data LTb.

Here, in the following description, in some cases, the latch data LTa output by the first latch circuit 224a included in the selection signal output portion 270[1] will be referred to as latch data LTai, and the latch data LTb output by the second latch circuit 224b included in the selection signal output portion 270[1] will be referred to as latch data LTbi. In some cases, the latch data LTa and LTb will be collectively referred to as latch data [LTa, LTb], and the latch data LTai and LTbi corresponding to the selection signal output portion 270[1] will be collectively referred to as latch data [LTai, LTbi].

The selection control signal Q0[SP00, SP01, SP02, SP03], the selection control signal Q1[SP10, SP11, SP12, SP13], the selection control signal Q2[SP20, SP21, SP22, SP23], and the selection control signal Q3[SP30, SP31, SP32, SP33] output by the selection control signal generation portion 262 are input in common to the decoder 226 included in each of the selection signal output portions 270[1] to 270[m], and the latch data [LTa, LTb] output by the corresponding first latch circuit 224a and second latch circuit 224b are input thereto. That is, the selection control signal Q0[SP00, SP01, SP02, SP03], the selection control signal Q1[SP10, SP11, SP12, SP13], the selection control signal Q2[SP20, SP21, SP22, SP23], AND the selection control signal Q3[SP30, SP31, SP32, SP33] output by the selection control signal generation portion 262, and the latch data [LTai, LTbi] corresponding to the ejection data [SIHi, SILi] are input to the decoder 226 included in the selection signal output portion 270[i]. The decoder 226 included in the selection signal output portion 270[i] generates the selection signal Sa[i] and Sb[i] by decoding the latch data [LTai, LTbi]

based on the selection control signals Q0, Q1, Q2, and Q3, and outputs the selection signal S[i] to the selection circuit 230[i].

FIG. 7 is a diagram illustrating decoding contents of the decoder 226 based on the selection control signals Q0, Q1, Q2, and Q3. As illustrated in FIG. 7, the decoder 226 outputs the selection signal Sa with a logic level defined by the selection control signal Q0[SP00, SP01, SP02, SP03] in the period t1, outputs the selection signal Sa with a logic level defined by the selection control signal Q1[SP10, SP11, SP12, SP13] in the period t2, outputs the selection signal Sb with a logic level defined by the selection control signal Q2[SP20, SP21, SP22, SP23] in the period t1, and outputs the selection signal Sb with a logic level defined by the selection control signal Q3[SP30, SP31, SP32, SP33] in the period t2.

Specifically, when the latch data [LTa, LTb]=[1,1] is input to the decoder 226, the decoder 226 outputs the selection signal Sa with the logic level corresponding to the setting information SP00 and the selection signal Sb with the logic level corresponding to the setting information SP20 in the period t1, and outputs the selection signal Sa with the logic level corresponding to the setting information SP10 and the selection signal Sb with the logic level corresponding to the setting information SP30 in the period t2, according to the contents defined by the selection control signals Q0, Q1, Q2, and Q3. Similarly, when the latch data [LTa, LTb]=[1, 0] is input to the decoder 226, the decoder 226 outputs the selection signal Sa with the logic level corresponding to the setting information SP01 and the selection signal Sb with the logic level corresponding to the setting information SP21 in the period t1, and outputs the selection signal Sa with the logic level corresponding to the setting information SP11 and the selection signal Sb with the logic level corresponding to the setting information SP31 in the period t2, according to the contents defined by the selection control signals Q0, Q1, Q2, and Q3. Similarly, when the latch data [LTa, LTb]=[0, 1] is input to the decoder 226, the decoder 226 outputs the selection signal Sa with the logic level corresponding to the setting information SP02 and the selection signal Sb with the logic level corresponding to the setting information SP22 in the period t1, and outputs the selection signal Sa with the logic level corresponding to the setting information SP12 and the selection signal Sb with the logic level corresponding to the setting information SP32 in the period t2, according to the contents defined by the selection control signals Q0, Q1, Q2, and Q3. Similarly, when the latch data [LTa, LTb]=[0,0] is input to the decoder 226, the decoder 226 outputs the selection signal Sa with the logic level corresponding to the setting information SP03 and the selection signal Sb with the logic level corresponding to the setting information SP32 in the period t1, and outputs the selection signal Sa with the logic level corresponding to the setting information SP13 and the selection signal Sb with the logic level corresponding to the setting information SP33 in the period t2, according to the contents defined by the selection control signals Q0, Q1, Q2, and Q3.

As described above, the selection control circuit 210 outputs the selection signals Sa[1] to Sa[m] and Sb[1] to Sb[m] for controlling states of the selection circuits 230[1] to 230[m] respectively corresponding to the piezoelectric elements 60[1] to 60[m] based on the clock signal SCK, the latch signal LAT, the change signal CH, and the head control signal DI.

Next, configurations of the selection circuits 230[1] to 230[m] will be described. Here, the selection circuits 230[1] to 230[m] all have the same configuration. Therefore, when

it is not necessary to distinguish the selection circuits 230[1] to 230[m], the selection circuits may be simply referred to as a selection circuit 230. A description will be made assuming that the selection signal Sa among the selection signals Sa[1] to Sa[m] and the selection signal Sb among the selection signals Sb[1] to Sb[m] are input to the selection circuit 230.

FIG. 8 is a diagram illustrating a configuration of the selection circuit 230 corresponding to the piezoelectric element 60. As illustrated in FIG. 8, the selection circuit 230 includes inverters 232a and 232b, which are NOT circuits, and transfer gates 234a and 234b.

While the selection signal Sa output by the selection control circuit 210 is input to a positive control end, which is not marked with a circle, at the transfer gate 234a, the selection signal S is logically inverted by the inverter 232a and is also input to a negative control end marked with a circle at the transfer gate 234a. In addition, the drive signal COMA is supplied to an input terminal of the transfer gate 234a. Specifically, the transfer gate 234a conducts the input end and the output end to each other when the input selection signal Sa is an H level, and does not conduct the input end and the output end to each other when the input selection signal Sa is an L level.

While the selection signal Sb output by the selection control circuit 210 is input to a positive control end that is not marked with a circle at the transfer gate 234b, the selection signal Sb is logically inverted by the inverter 232b and is also input to a negative control end that is marked with a circle at the transfer gate 234b. The drive signal COMB is supplied to an input end of the transfer gate 234b. Specifically, the transfer gate 234b conducts the input end and the output end to each other when the input selection signal Sb has an H level, and does not conduct the input end and the output end to each other when the input selection signal Sb has an L level.

The drive signal VOUT is output from a connection point in which the output end of the transfer gate 234a and the output end of the transfer gate 234b are commonly coupled.

As described above, the drive signal selection circuit 200 according to the present embodiment selects or does not select signal waveforms of the drive signals COMA and COMB based on the input clock signal SCK, latch signal LAT, change signal CH, and head control signal DI to generate the drive signals VOUT[1] to VOUT[m] respectively corresponding to the piezoelectric elements 60[1] to 60[m], and outputs the drive signals VOUT[1] to VOUT[m] to the corresponding piezoelectric elements 60[1] to 60[m].

Here, an example of a specific operation of the drive signal selection circuit 200 will be described. The drive signal selection circuit 200 generates the drive signal VOUT by selecting or not selecting signal waveforms of the drive signals COMA and COMB, and outputs the drive signal VOUT to the first end of the piezoelectric element 60. Thus, in describing an example of the specific operation of the drive signal selection circuit 200, a specific example of the signal waveforms of the drive signals COMA and COMB input to the drive signal selection circuit 200 will be described.

FIG. 9 is a diagram illustrating an example of signal waveforms of the drive signals COMA and COMB. As illustrated in FIG. 9, the drive signal COMA is a signal including a signal waveform in which a trapezoidal waveform Adp1 disposed in the period t1 after the latch signal LAT rises until the change signal CH rises and a trapezoidal waveform Adp2 disposed in the period t2 after the change signal CH rises until the latch signal LAT rises are continu-

ous. The drive signal COMB is a signal including a signal waveform in which a trapezoidal waveform Bdp1 disposed in the period t1 and a trapezoidal waveform Bdp2 disposed in the period t2 are continuous.

The trapezoidal waveform Adp1 is a signal waveform for driving the piezoelectric element 60 to eject a predetermined amount of ink from a corresponding nozzle when supplied to the piezoelectric element 60, and the trapezoidal waveform Adp2 is a signal waveform for driving the piezoelectric element 60 to eject an amount of ink smaller than the predetermined amount from a corresponding nozzle when supplied to the piezoelectric element 60. The trapezoidal waveform Bdp1 is a signal waveform for driving the piezoelectric element 60 to eject an amount of ink smaller than the predetermined amount from a corresponding nozzle when supplied to the piezoelectric element 60, and the trapezoidal waveform Bdp2 is a signal waveform for driving the piezoelectric element 60 not to eject ink from a corresponding nozzle even when supplied to the piezoelectric element 60.

The trapezoidal waveform Bdp2 is a signal waveform for vibrating the ink in the vicinity of the nozzle opening portion of the nozzle to prevent an increase in ink viscosity. In the following description, when the trapezoidal waveform Bdp2 is supplied to the piezoelectric element 60, an operation of vibrating the ink in the vicinity of the opening portion of the nozzle may be referred to as micro-vibration. In the following description, an amount of ink ejected when the trapezoidal waveform Adp1 is supplied to the piezoelectric element 60 may be referred to as a medium amount, and an amount of ink ejected when the trapezoidal waveform Adp2 and Bdp1 are supplied to the piezoelectric element 60 may be referred to as a small amount.

Both the voltage values at start timings and end timings of the trapezoidal waveforms Adp1, Adp2, Bdp1, and Bdp2 are a voltage Vc which is a common voltage. In other words, each of the trapezoidal waveforms Adp1, Adp2, Bdp1, and Bdp2 starts at the voltage Vc and ends at the voltage Vc. The cycle tp including the periods t1 and t2 corresponds to a dot formation cycle for forming new dots on the medium P.

FIG. 10 is a diagram illustrating an example of the head control signal DI input to the drive signal selection circuit 200. Here, the ejection control signal SI included in the head control signal DI defines an ejection amount of the ink ejected by driving the piezoelectric element 60. Therefore, a logic level of the ejection control signal SI appropriately changes during a printing period in which the liquid ejection apparatus 1 ejects the ink and forms a desired image on the medium P. That is, the logic level of the ejection data [SIH, SIL] included in the ejection control signal SI changes to either 0 or 1 according to an amount of the ejected ink. In other words, the logic level of the ejection data [SIH, SIL] included in the ejection control signal SI changes for each cycle tp according to an image formed on the medium P. Therefore, in FIG. 10, only a specific logic level for the waveform selection signal SP is illustrated, and a specific logic level for the ejection control signal SI is not illustrated.

As illustrated in FIG. 10, the head control signal DI including the waveform selection signal SP in which the setting information SP00, SP01, SP02, SP03, SP10, SP11, SP12, SP13, SP20, SP21, SP22, SP23, SP30, SP31, SP32, and SP33 are respectively “1”, “0”, “0”, “0”, “0”, “1”, “1”, “1”, “0”, “0”, “1”, “0”, “0”, “0”, “0”, “0”, and “1” is input to the drive signal selection circuit 200. Therefore, based on the waveform selection signal SP, the selection control signal Q0[SP00, SP01, SP02, SP03]=[1, 0, 0, 0], the selection control signal Q1[SP10, SP11, SP12, SP13]=[1, 1, 0, 0], the selection control signal Q2[SP20, SP21, SP22,

SP23]=[0, 1, 0, 0], and the selection control signal Q3[SP30, SP31, SP32, SP33]=[0, 0, 0, 1] are generated by the selection control signal generation portion 262 included in the control logic circuit 260 and output to the decoder 226.

FIG. 11 is a diagram illustrating a specific example of the decoding contents of the decoder 226 when the head control signal DI including the waveform selection signal SP described above is input to the drive signal selection circuit 200. A description will be made assuming that the decoder 226 of the present embodiment outputs the selection signal S with an H level when logic levels of the corresponding setting information SP33 to SP30, SP23 to SP20, SP13 to SP10, and SP03 to SP00 are “1”, and outputs the selection signal S with an L level when logic levels of the corresponding setting information SP33 to SP30, SP23 to SP20, SP13 to SP10, and SP03 to SP00 are “0”.

As illustrated in FIG. 11, when the latch data [LTa, LTb]=[1, 1] corresponding to the ejection data [SIH, SIL]=[1, 1] is input to the decoder 226, the decoder 226 outputs the selection signal Sa with H and H levels in the periods t1 and t2, and the selection signal Sb with L and L levels in the periods t1 and t2. When the latch data [LTa, LTb]=[1, 0] corresponding to the ejection data [SIH, SIL]=[1, 0] is input to the decoder 226, the decoder 226 outputs the selection signal Sa with L and H levels in the periods t1 and t2, and the selection signal Sb with H and L levels in the periods t1 and t2. When the latch data [LTa, LTb]=[0, 1] corresponding to the ejection data [SIH, SIL]=[0, 1] is input to the decoder 226, the decoder 226 outputs the selection signal Sa with L and H levels in the periods t1 and t2, and the selection signal Sb with L and L levels in the periods t1 and t2. When the latch data [LTa, LTb]=[0, 0] corresponding to the ejection data [SIH, SIL]=[0, 0] is input to the decoder 226, the decoder 226 outputs the selection signal Sa with L and L levels in the periods t1 and t2, and the selection signal Sb with L and H levels in the periods t1 and t2.

FIG. 12 is a diagram illustrating the drive signal VOUT output from the selection circuit 230 when the selection signals Sa and Sb illustrated in FIG. 11 are supplied.

As illustrated in FIG. 12, when the latch data [LTa, LTb]=[1, 1] is input to the decoder 226, the logic level of the selection signal Sa is set to an H level in the period t1 and an H level in the period t2, and the logic level of the selection signal Sb is set to an L level in the period t1 and an L level in the period t2. Accordingly, the selection circuit 230 selects the trapezoidal waveform Adp1 in the period t1 and selects the trapezoidal waveform Adp2 in the period t2. That is, the selection circuit 230 outputs the drive signal VOUT having a signal waveform in which the trapezoidal waveform Adp1 and the trapezoidal waveform Adp2 are continuous. In this case, by driving the piezoelectric element 60, a medium amount of ink is ejected in the period t1, and a small amount of ink is ejected in the period t2. As a result, in the cycle tp, a medium amount of ink and a small amount of ink landing on the medium P are combined to form a large dot on the medium P.

When the latch data [LTa, LTb]=[1, 0] is input to the decoder 226, the logic level of the selection signal Sa is set to an L level in the period t1 and an H level in the period t2, and the logic level of the selection signal Sb is set to an H level in the period t1 and an L level in the period t2. Accordingly, the selection circuit 230 selects the trapezoidal waveform Bdp1 in the period t1 and selects the trapezoidal waveform Adp2 in the period t2. That is, the selection circuit 230 outputs the drive signal VOUT having a signal waveform in which the trapezoidal waveform Bdp1 and the trapezoidal waveform Adp2 are continuous. In this case, by

driving the piezoelectric element 60, a small amount of ink is ejected in the period t1, and a small amount of ink is ejected in the period t2. As a result, in the cycle tp, a small amount of ink landing on the medium P and a small amount of ink are combined to form a medium dot on the medium P.

When the latch data [LTa, LTb]=[0, 1] is input to the decoder 226, the logic level of the selection signal Sa is set to an L level in the period t1 and an H level in the period t2, and the logic level of the selection signal Sb is set to an L level in the period t1 and an L level in the period t2. Accordingly, the selection circuit 230 selects neither of trapezoidal waveforms Adp1 and Bdp1 in the period t1 and selects the trapezoidal waveform Adp2 in the period t2. That is, the selection circuit 230 outputs the drive signal VOUT having a signal waveform in which a constant signal waveform at the voltage Vc and the trapezoidal waveform Adp2 are continuous. In this case, by driving the piezoelectric element 60, the ink is not ejected in the period t1, and a small amount of ink is ejected in the period t2. As a result, in the cycle tp, a small dot is formed on the medium P by a small amount of ink landing on the medium P.

When the latch data [LTa, LTb]=[0, 0] is input to the decoder 226, the logic level of the selection signal Sa is set to an L level in the period t1 and an L level in the period t2, and the logic level of the selection signal Sb is set to an L level in the period t1 and an H level in the period t2. Accordingly, the selection circuit 230 selects neither of trapezoidal waveforms Adp1 and Bdp1 in the period t1 and selects the trapezoidal waveform Bdp2 in the period t2. That is, the selection circuit 230 outputs the drive signal VOUT having a signal waveform in which a constant signal waveform at the voltage Vc and the trapezoidal waveform Bdp2 are continuous. In this case, by driving the piezoelectric element 60, the ink is not ejected in the period t1 and the ink is not ejected even in the period t2. As a result, in the cycle tp, a dot is not formed on the medium P, and micro-vibration is executed.

Here, in the drive signal VOUT output by the drive signal selection circuit 200, a signal waveform in which one of the trapezoidal waveforms Adp1 and Adp2 included in the drive signal COMA and one of the trapezoidal waveforms Bdp1 and Bdp2 included in the drive signal COMB are selected and a signal waveform that is constant at the voltage Vc stored in a capacitive component of the piezoelectric element 60 to which the drive signal VOUT is supplied are continuous. That is, the drive signal VOUT output by the drive signal selection circuit 200 is synonymous with the drive signal VOUT supplied to the piezoelectric element 60. That is, the piezoelectric element 60 of the present embodiment is driven by receiving the drive signal COMA or the drive signal COMB, and the print head 20 ejects ink by receiving the drive signal COMA and the drive signal COMB.

5. Structure of Ejection Module 22 Included in Print Head 20

Next, a structure of the ejection module 22 included in the print head 20 will be described. FIG. 13 is an exploded perspective view illustrating the structure of the ejection module 22, FIG. 14 is a plan view of the ejection module 22, and FIG. 15 is a sectional view taken along the line XV-XV in FIG. 14, FIG. 16 is a detailed view of a main portion IN FIG. 15, and FIG. 17 is a sectional view taken along the line XVII-XVII in FIG. 14. In describing the structure of the print head 20, X, Y, and Z are illustrated in respective three spatial axes orthogonal to each other. In the present embodiment, directions along these axes are referred to as an X-axis

direction, a Y-axis direction, and a Z-axis direction, and when the directions are specified, the positive direction is indicated by “+” and the negative direction is indicated by “-”. Positive and negative signs are used together with the direction notations, a direction in which an arrow in each drawing is directed will be described as the + direction, and an opposite direction of the arrow will be described as the - direction. The Z-axis direction indicates a vertical direction, the +Z direction indicates a vertical downward direction, and the -Z direction indicates a vertical upward direction. The three X, Y, and Z spatial axes that do not limit the positive direction and the negative direction will be described as the X axis, the Y axis, and the Z axis.

As illustrated in FIG. 13, the ejection module 22 ejects ink in the Z-axis direction, more specifically, in the +Z-axis direction. The ejection module 22 includes a pressure chamber substrate 310, a communication plate 315, a nozzle plate 320, a compliance substrate 345, a vibration plate 350 that will be described later, a piezoelectric element 60 that will be described later, a protective substrate 330, a case member 340, and a wiring substrate 420 as constituent members.

The pressure chamber substrate 310 is formed of, for example, a silicon substrate, a glass substrate, an SOI substrate, various ceramic substrates, or the like. As illustrated in FIG. 14, on the pressure chamber substrate 310, two rows of pressure chambers in which a plurality of pressure chambers 312 are arranged in the Y-axis direction are disposed in the X-axis direction. In other words, the ejection module 22 included in the print head 20 has a plurality of pressure chambers 312, and the plurality of pressure chambers 312 form a pressure chamber row in which the plurality of pressure chambers 312 are arranged in the Y-axis direction. Here, out of the two pressure chamber rows, the pressure chamber row on the +X direction side may be referred to as a first pressure chamber row, and the pressure chamber row separated from the first pressure chamber row in the -X direction in the X-axis direction may be referred to as a second pressure chamber row. Although FIG. 14 is a plan view of the ejection module 22, a configuration around the pressure chamber substrate 310 is illustrated, and the protective substrate 330 and the case member 340 are not illustrated.

The plurality of pressure chambers 312 configuring each pressure chamber row are disposed on a straight line in the Y-axis direction such that positions thereof in the X-axis direction are the same position. The pressure chambers 312 adjacent to each other in the Y-axis direction are partitioned by a partition wall 311 illustrated in FIG. 17. Of course, the disposition of the pressure chamber 312 is not particularly limited. For example, the disposition of the plurality of pressure chambers 312 arranged in the Y-axis direction may be a so-called staggered disposition in which the respective pressure chambers 312 are disposed at positions shifted in the X-axis direction for every other pressure chamber 312.

The pressure chamber 312 of the present embodiment is formed in a rectangular shape, for example, in which a length in the X-axis direction is longer than a length in the Y-axis direction in a plan view from the +Z direction. Of course, a shape of the pressure chamber 312 in a plan view from the +Z direction is not particularly limited, and may be a parallel quadrilateral shape, a polygonal shape, a circular shape, an oval shape, or the like. The oval shape referred to here is a shape in which both end portions in a longitudinal direction are semicircular based on a rectangular shape, and includes a rounded rectangular shape, an elliptical shape, an egg shape, and the like.

As illustrated in FIGS. 13 and 16, the communication plate 315, the nozzle plate 320, and the compliance substrate 345 are stacked in order on the +Z direction side of the pressure chamber substrate 310.

The communication plate 315 is provided with a nozzle communication path 316 via which the pressure chamber 312 and the nozzle 321 communicate with each other. The communication plate 315 is provided with a first manifold portion 317 and a second manifold portion 318 that form a part of a manifold 400 that serves as a common liquid chamber with which the plurality of pressure chambers 312 communicate. The first manifold portion 317 is provided to penetrate the communication plate 315 in the Z-axis direction. The second manifold portion 318 is provided to be open on the surface on the +Z direction side without penetrating the communication plate 315 in the Z-axis direction.

The communication plate 315 is provided with a supply communication path 319 communicating with a first end portion of the pressure chamber 312 in the X-axis direction independently of each of the pressure chambers 312. The supply communication path 319 causes the second manifold portion 318 to communicate with each of the pressure chambers 312, and supplies the ink in the manifold 400 to each pressure chamber 312.

As the communication plate 315, a silicon substrate, a glass substrate, an SOI substrate, various ceramic substrates, a metal substrate, or the like may be used. Examples of the metal substrate include a stainless steel substrate. It is preferable that the communication plate 315 is formed by using a material having a thermal expansion coefficient substantially the same as a thermal expansion coefficient of the pressure chamber substrate 310. As a result, when the temperatures of the pressure chamber substrate 310 and the communication plate 315 change, it is possible to suppress the warpage of the pressure chamber substrate 310 and the communication plate 315 due to a difference between the thermal expansion coefficients.

The nozzle plate 320 is provided on the surface the communication plate 315 on the opposite side to the pressure chamber substrate 310, that is, on the surface on the +Z direction side. The nozzle plate 320 is provided with nozzles 321 communicating with the respective pressure chambers 312 via the nozzle communication paths 316.

In the present embodiment, a plurality of nozzles 321 are disposed to be arranged in a row in the Y-axis direction. The nozzle plate 320 is provided with two nozzle rows with a gap in the X-axis direction in which the plurality of nozzles 321 are arranged in a row. The two nozzle rows correspond to the first pressure chamber row and the second pressure chamber row, respectively. That is, the plurality of nozzles 321 in each row are disposed such that positions in the X-axis direction are the same position. The disposition of the nozzle 321 is not particularly limited. For example, the nozzles 321 disposed to be arranged in the Y-axis direction may be disposed at positions shifted in the X-axis direction for every other nozzle 321.

A material of the nozzle plate 320 is not particularly limited, and for example, a silicon substrate, a glass substrate, an SOI substrate, various ceramic substrates, and a metal substrate may be used. Examples of the metal substrate include a stainless steel substrate. As a material of the nozzle plate 320, an organic substance such as a polyimide resin may be used. However, it is preferable to use a material for the nozzle plate 320 that has substantially the same thermal expansion coefficient as the thermal expansion coefficient of the communication plate 315. As a result, when the temperatures of the nozzle plate 320 and the

communication plate 315 change, it is possible to suppress the warpage of the nozzle plate 320 and the communication plate 315 due to a difference in the thermal expansion coefficient.

5 The compliance substrate 345 is provided together with the nozzle plate 320 on the surface of the communication plate 315 on the opposite side to the pressure chamber substrate 310, that is, on the surface on the +Z direction side. The compliance substrate 345 is provided around the nozzle plate 320 and seals the openings of the first manifold portion 317 and the second manifold portion 318 provided in the communication plate 315. The compliance substrate 345 includes a sealing film 346 formed of a flexible thin film and a fixed substrate 347 made of a hard material such as metal. 10 A region of the fixed substrate 347 facing the manifold 400 is an opening portion 348 completely removed in the thickness direction. Thus, one surface of the manifold 400 is a compliance portion 349 sealed only by the flexible sealing film 346.

15 On the other hand, on the surface of the pressure chamber substrate 310 on the opposite side to the nozzle plate 320 or the like, that is, on the surface on the -Z direction side, the vibration plate 350 and the piezoelectric element 60 that bends and deforms the vibration plate 350 to cause a pressure change in the ink inside the pressure chamber 312, which will be described in detail later, are stacked. In other words, the vibration plate 350 is provided in the +Z-axis direction of the Z-axis direction with respect to the piezoelectric element 60, and the pressure chamber substrate 310 20 is provided in the +Z-axis direction of the Z-axis direction with respect to the vibration plate 350. Note that FIG. 15 is a diagram for describing the overall configuration of the ejection module 22, and the configuration of the piezoelectric element 60 is simplified and illustrated.

25 The protective substrate 330 having substantially the same size as that of the pressure chamber substrate 310 is further bonded to the surface of the pressure chamber substrate 310 on the -Z direction side via an adhesive or the like. The protective substrate 330 has a holding portion 331 that is a space for protecting the piezoelectric element 60. 30 The holding portions 331 are provided independently for each row of the piezoelectric elements 60 disposed to be arranged in the Y-axis direction, and two holding portions 331 are formed to be arranged in the X-axis direction. The protective substrate 330 is provided with a through-hole 332 35 penetrating in the Z-axis direction between the two holding portions 331 disposed to be arranged in the X-axis direction.

40 The case member 340 for defining the manifold 400 communicating with the plurality of pressure chambers 312 together with the pressure chamber substrate 310 is fixed on the protective substrate 330. The case member 340 has substantially the same shape as that of the communication plate 315 described above in a plan view in the +Z direction, and is bonded to the protective substrate 330 and also to the 45 communication plate 315 described above.

45 Such a case member 340 has an accommodating portion 341 that is a space having a depth configured to accommodate the pressure chamber substrate 310 and the protective substrate 330 on the side of the protective substrate 330. The 50 accommodating portion 341 has an opening area wider than the surface of the protective substrate 330 bonded to the pressure chamber substrate 310. The opening surface of the accommodating portion 341 on the side of the nozzle plate 320 is sealed by the communication plate 315 in a state in which the pressure chamber substrate 310 and the protective substrate 330 are accommodated in the accommodating portion 341.

In the case member 340, third manifold portions 342 are defined on both of the outsides of the accommodating portion 341 in the X-axis direction. The manifold 400 of the present embodiment is constituted with the first manifold portion 317 and the second manifold portion 318 provided on the communication plate 315, and the third manifold portion 342. The manifold 400 is continuously provided in the Y-axis direction, and the supply communication paths 319 via which each of the pressure chambers 312 and the manifold 400 communicate with each other are disposed to be arranged in the Y-axis direction.

The case member 340 is provided with a supply port 344 that communicates with the manifolds 400 to supply ink to each of the manifolds 400. The case member 340 is provided with a coupling port 343 that communicates with the through-hole 332 of the protective substrate 330 and into which the wiring substrate 420 is inserted.

In the ejection module 22 of the present embodiment, after the ink stored in the ink container 2 is incorporated from the supply port 344 and the inside from the manifold 400 to the nozzle 321 is filled with the ink, the drive signal VOUT based on the drive signal COM is supplied from the integrated circuit 421 including the drive signal selection circuit 200 to each of the piezoelectric elements 60 corresponding to the pressure chamber 312. As a result, the vibration plate 350 is bent and deformed together with the piezoelectric element 60, the pressure in each pressure chamber 312 increases, and the ink is ejected from each nozzle 321. The print head 20 is configured to have a plurality of the above-described ejection modules 22.

Next, a configuration of the pressure chamber substrate 310 including the vibration plate 350 and the piezoelectric element 60 described above, which are stacked and formed on the -Z-axis direction side, will be described in detail. The ejection module 22 has an individual lead electrode 391, a common lead electrode 392, a measurement lead electrode 393, and a resistance wiring 401 as constituents stacked on the -Z-axis direction side of the pressure chamber substrate 310, in addition to the vibration plate 350 and the piezoelectric element 60.

As illustrated in FIGS. 15 to 17, the vibration plate 350 includes an elastic film 351, which is made of silicon oxide, provided on the side of the pressure chamber substrate 310, and an insulator film 352, which is made of a zirconium oxide film, provided on the elastic film 351. The liquid flow path of the pressure chamber 312 or the like is formed through anisotropic etching of the pressure chamber substrate 310 from the surface on the +Z direction side, and the surface of the liquid flow path of the pressure chamber 312 or the like on the -Z direction side is formed of the elastic film 351.

A configuration of the vibration plate 350 is not particularly limited. The vibration plate 350 may be formed of, for example, either the elastic film 351 or the insulator film 352, and may further include other films other than the elastic film 351 and the insulator film 352. Examples of a material of the other film include silicon and silicon nitride.

The piezoelectric element 60 is an example of a piezoelectric actuator that causes a pressure change in the ink in the pressure chamber 312. The piezoelectric element 60 has a first electrode 360, a piezoelectric body 370, and a second electrode 380 sequentially stacked from the +Z-axis direction side that is the vibration plate 350 side toward the -Z-axis direction side. In other words, the piezoelectric element 60 includes the first electrode 360, the second electrode 380, and the piezoelectric body 370, and the piezoelectric body 370 is provided between the first elec-

trode 360 and the second electrode 380 in the Z-axis direction in which the first electrode 360, the second electrode 380, and the piezoelectric body 370 are stacked.

Both the first electrode 360 and the second electrode 380 are electrically coupled to the wiring substrate 420, and supply the drive signal VOUT supplied from the drive signal selection circuit 200 included in the integrated circuit 421 mounted on the wiring substrate 420 and the reference voltage signal VBS propagating through the wiring substrate 420, to the piezoelectric body 370. A different drive signal VOUT is supplied to the first electrode 360 according to an ejection amount of ink, and the constant reference voltage signal VBS is supplied to the second electrode 380 regardless of an ejection amount of ink. As a result, a potential difference is generated between the first electrode 360 and the second electrode 380, and thus the piezoelectric body 370 is deformed. That is, when the piezoelectric element 60 is driven, the vibration plate 350 is deformed or vibrated, and the volume of the pressure chamber 312 changes, so that pressure is applied to the ink stored in the pressure chamber 312. As a result, the ink is ejected from the nozzle 321 via the nozzle communication path 316. In this case, a volume change amount of the pressure chamber 312 is an ink ejection amount.

When a voltage is applied between the first electrode 360 and the second electrode 380 in the piezoelectric element 60, a portion at which piezoelectric distortion occurs in the piezoelectric body 370 will be referred to as an active portion 410. On the other hand, a portion where piezoelectric distortion does not occur in the piezoelectric body 370 will be referred to as an inactive portion 415. That is, in the piezoelectric element 60, a portion where the piezoelectric body 370 is interposed between the first electrode 360 and the second electrode 380 is the active portion 410, and a portion where the piezoelectric body 370 is not interposed between the first electrode 360 and the second electrode 380 is the inactive portion 415. When the piezoelectric element 60 is driven, a portion that is displaced in the Z-axis direction will be referred to as a flexible portion, and a portion that is not displaced in the Z direction will be referred to as a non-flexible portion. That is, in the piezoelectric element 60, a portion facing the pressure chamber 312 in the Z-axis direction is the flexible portion, and an outer portion of the pressure chamber 312 is the non-flexible portion. The active portion 410 will also be referred to as a proactive portion, and the inactive portion 415 will also be referred to as a passive portion.

Generally, one electrode of the active portion 410 is configured as an independent individual electrode for each active portion 410, and the other electrode is configured as a common electrode common to a plurality of active portions 410. In the present embodiment, the first electrode 360 is configured as an individual electrode, and the second electrode 380 is configured as a common electrode.

Specifically, the first electrode 360 is provided on the +Z-axis direction side in the Z-axis direction with respect to the piezoelectric body 370, is separated for each pressure chamber 312, and configures an individual electrode that is independent for each active portion 410. The first electrode 360 is individually provided for the plurality of pressure chambers 312. The first electrode 360 is formed to have a width smaller than the width of the pressure chamber 312 in the Y-axis direction. That is, the end portion of the first electrode 360 is located on the inside of the region facing the pressure chamber 312 in the Y-axis direction.

An end portion 360a in the +X direction and an end portion 360b in the -X direction of the first electrode 360 are

disposed on the outside of the pressure chamber 312. For example, in the first pressure chamber row, as illustrated in FIG. 16, the end portion 360a of the first electrode 360 is disposed at a position further toward the +X direction side than the end portion 312a of the pressure chamber 312 in the +X direction. The end portion 360b of the first electrode 360 is disposed at a position further toward the -X direction side than the end portion 312b of the pressure chamber 312 in the -X direction.

A material of the first electrode 360 is not particularly limited, and, for example, metals such as platinum (Pt), iridium (Ir), gold (Au), and titanium (Ti), and conductive materials including conductive metal oxides such as indium tin oxide abbreviated to ITO may be used. Alternatively, a plurality of materials such as platinum (Pt), iridium (Ir), gold (Au), and titanium (Ti) may be stacked and formed. In the present embodiment, platinum (Pt) is used as the first electrode 360.

As illustrated in FIG. 14, the piezoelectric body 370 is continuously provided in the Y-axis direction with a length in the X-axis direction as a predetermined length. That is, the piezoelectric body 370 has a predetermined thickness and is continuously provided in the direction in which the pressure chambers 312 are arranged. A thickness of the piezoelectric body 370 is not particularly limited, and may be about 1000 nanometers to 4000 nanometers.

As illustrated in FIG. 16, a length of the piezoelectric body 370 in the X-axis direction is larger than a length of the pressure chamber 312 in the X-axis direction that is a longitudinal direction. Therefore, on both sides of the pressure chamber 312 in the X-axis direction, the piezoelectric body 370 extends to the outside of the pressure chamber 312. As described above, the piezoelectric body 370 extends to the outside of the pressure chamber 312 in the X-axis direction, and thus the strength of the vibration plate 350 is improved. Therefore, when the active portion 410 is driven to displace the piezoelectric element 60, it is possible to suppress the occurrence of cracks or the like in the vibration plate 350 or the piezoelectric element 60.

As illustrated in FIG. 16, the end portion 370a of the piezoelectric body 370 in the +X direction is located toward the +X direction side that is an outer side than the end portion 360a of the first electrode 360 in the first pressure chamber row. That is, the end portion 360a of the first electrode 360 is covered with the piezoelectric body 370. On the other hand, the end portion 370b of the piezoelectric body 370 in the -X direction is located toward the +X direction side which is an inner side than the end portion 360b of the first electrode 360, and the end portion 360b of the first electrode 360 is not covered with the piezoelectric body 370.

As illustrated in FIGS. 14 and 17, the piezoelectric body 370 is formed with a groove portion 371 to correspond to each of the partition walls 311 and having a thickness smaller than that of the other regions. The groove portion 371 of the present embodiment is formed by completely removing the piezoelectric body 370 in the Z-axis direction. That is, the fact that the piezoelectric body 370 has a portion having a thickness smaller than the other regions includes a case where the piezoelectric body 370 is completely removed in the Z-axis direction. Of course, the piezoelectric body 370 may be formed thinner than the other portions on the bottom surface of the groove portion 371.

The length of the groove portion 371 in the Y-axis direction, that is, a width of the groove portion 371 is the same as or larger than the width of the partition wall 311. In

the present embodiment, the width of the groove portion 371 is larger than the width of the partition wall 311.

The groove portion 371 is formed in a rectangular shape in a plan view from the -Z direction side. Of course, a shape of the groove portion 371 in a plan view from the -Z direction side is not limited to a rectangular shape, and may be a polygonal shape of pentagon or more, a circular shape, an elliptical shape, or the like.

By providing the groove portion 371 in the piezoelectric body 370, the rigidity of the portion of the vibration plate 350 facing the end portion of the pressure chamber 312 in the Y-axis direction, that is, a so-called arm portion of the vibration plate 350 is suppressed, and thus the piezoelectric element 60 can be favorably displaced.

Examples of the piezoelectric body 370 include a crystal film having a perovskite structure formed on the first electrode 360 and made of a ferroelectric ceramic material exhibiting an electromechanical conversion action, that is, a so-called perovskite type crystal. As a material of the piezoelectric body 370, for example, a ferroelectric piezoelectric material such as lead zirconate titanate (PZT) or a material to which a metal oxide such as niobium oxide, nickel oxide, or magnesium oxide is added may be used. Specifically, lead titanate ($PbTiO_3$), lead zirconate titanate ($Pb(Zr,Ti)O_3$), lead zirconate ($PbZrO_3$), lead lanthanum titanate ($(Pb,La)TiO_3$), lead lanthanum zirconate titanate ($(Pb,La)(Zr,Ti)O_3$), lead magnesium niobate zirconate ($Pb(Zr,Ti)(Mg,Nb)O_3$), or the like may be used. In the present embodiment, lead zirconate titanate (PZT) is used as the piezoelectric body 370.

The material of the piezoelectric body 370 is not limited to a lead-based piezoelectric material containing lead, and a lead-free piezoelectric material containing no lead may also be used. Examples of the non-lead-based piezoelectric material include bismuth iron acid ($(BiFeO_3)$, abbreviated to "BFO"), barium titanate ($(BaTiO_3)$, abbreviated to "BT"), potassium sodium niobate ($(K,Na)(NbO_3)$, abbreviated to "KNN"), potassium sodium lithium niobate ($(K,Na,Li)(NbO_3)$), potassium sodium lithium tantalate niobate ($(K,Na,Li)(Nb,Ta)O_3$), bismuth potassium titanate ($(Bi_{1/2}K_{1/2})TiO_3$, abbreviated to "BKT"), bismuth sodium titanate ($(Bi_{1/2}Na_{1/2})TiO_3$, abbreviated to "BNT"), bismuth manganate ($BiMnO_3$, abbreviated to "BM"), a composite oxide containing bismuth, potassium, titanium, and iron and having a perovskite structure ($x[(Bi_xK_{1-x})TiO_3]-(1-x)[BiFeO_3]$, abbreviated to "BKT-BF"), a composite oxide containing bismuth, iron, barium, and titanium and having a perovskite structure ($(1-x)[BiFeO_3]-x[BaTiO_3]$, abbreviated to "BFO-BT"), and a material ($(1-x)[Bi(Fe_{1-y}M_y)O_3]-x[BaTiO_3]$, M being Mn, Co, or Cr), which is obtained by adding metals such as manganese, cobalt, and chromium to the composite oxide.

As illustrated in FIGS. 14, 16, and 17, the second electrode 380 is provided on the -Z direction side of the Z-axis direction which is the opposite side to the first electrode 360 with respect to the piezoelectric body 370, and is configured as a common electrode common to the plurality of active portions 410. The second electrode 380 is provided in common to the plurality of pressure chambers 312. The second electrode 380 is continuously provided in the Y-axis direction with a length in the X-axis direction as a predetermined length. The second electrode 380 is also provided on the inner surface of the groove portion 371, that is, on the side surface of the groove portion 371 of the piezoelectric body 370, and on the insulator film 352 which is the bottom surface of the groove portion 371. Regarding the inside of the groove portion 371, the second electrode 380 may be

provided only on a part of the inner surface of the groove portion 371, or does not need to be provided over the entire surface of the inner surface of the groove portion 371.

As illustrated in FIG. 16, in the first pressure chamber row, the end portion 380a of the second electrode 380 in the +X direction is disposed toward the +X direction side that is an outer side than the end portion 360a of the first electrode 360 covered with the piezoelectric body 370. That is, the end portion 380a of the second electrode 380 is located toward the +X-axis direction side that is an outer side than end portion 312a of the pressure chamber 312, and toward the +X-axis direction side that is an outer side than the end portion 360a of the first electrode 360. In the present embodiment, the end portion 380a of the second electrode 380 substantially coincides with the end portion 370a of the piezoelectric body 370 in the X-axis direction. Accordingly, the end portion of the active portion 410 in the +X direction, that is, the boundary between the active portion 410 and the inactive portion 415 is defined by the end portion 360a of the first electrode 360.

The end portion 380b of the second electrode 380 in the -X direction is disposed toward the -X direction side that is an outer side than the end portion 312b of the pressure chamber 312 in the -X direction, and is disposed toward the +X direction side that is an inner side than the end portion 370b of the piezoelectric body 370. As described above, the end portion 370b of the piezoelectric body 370 is located toward the +X direction side that is an inner side than the end portion 360b of the first electrode 360. Therefore, the end portion 380b of the second electrode 380 is located on the piezoelectric body 370 further toward the +X direction side than the end portion 360b of the first electrode 360. There is a portion to which the surface of the piezoelectric body 370 is exposed on the end portion 380b of the second electrode 380 on the -X direction side.

As described above, the end portion 380b of the second electrode 380 is disposed further toward the +X direction side than the end portion 370b of the piezoelectric body 370 and the end portion 360b of the first electrode 360. Therefore, the end portion of the active portion 410 in the -X direction, that is, the boundary between the active portion 410 and the inactive portion 415 is defined by the end portion 380b of the second electrode 380.

A material of the second electrode 380 is not particularly limited, but, similar to the first electrode 360, for example, metals such as platinum (Pt), iridium (Ir), gold (Au), and titanium (Ti), and conductive materials including conductive metal oxides such as indium tin oxide abbreviated to ITO may be used. Alternatively, a plurality of materials such as platinum (Pt), iridium (Ir), gold (Au), and titanium (Ti) may be stacked and formed. In the present embodiment, iridium (Ir) is used as the second electrode 380.

On the outside of the end portion 380b of the second electrode 380, that is, further in the -X direction of the end portion 380b of the second electrode 380, a wiring portion 385 that is formed at the same layer as the second electrode 380 but is electrically decoupled from the second electrode 380 is provided. The wiring portion 385 is formed from above of the piezoelectric body 370 to above of the first electrode 360 extending further in the -X direction than the piezoelectric body 370 in a state in which the wiring portion 385 is spaced not to be in contact with the end portion 380b of the second electrode 380. The wiring portion 385 is provided independently for each of the active portions 410. That is, a plurality of wiring portions 385 are disposed at predetermined intervals in the Y-axis direction. The wiring portion 385 may be formed of a layer different from that of

the second electrode 380, but is preferably formed of the same layer as the second electrode 380. As a result, manufacturing steps of the wiring portion 385 can be simplified and the cost can be reduced.

- 5 For the first electrode 360 and the second electrode 380 configuring the piezoelectric element 60, the individual lead electrode 391 is electrically coupled to the first electrode 360 and the common lead electrode 392 that is a driving common electrode is electrically coupled to the second electrode 380.
 10 The flexible wiring substrate 420 is electrically coupled to the end portions of the individual lead electrode 391 and the common lead electrode 392 on the opposite side to the end portions coupled to the piezoelectric element 60. The control mechanism 10, the temperature information output circuit 26, and a plurality of wirings for coupling to a plurality of circuits (not illustrated) are formed on the wiring substrate 420. In the present embodiment, the wiring substrate 420 is configured with, for example, a flexible printed circuit (FPC). Any flexible substrate such as flexible flat cable (FFC) may be used instead of an FPC.

In the present embodiment, the individual lead electrode 391 and the common lead electrode 392 extend to be exposed in the through-hole 332 formed in the protective substrate 330, and are electrically coupled to the wiring substrate 420 in the through-hole 332. The integrated circuit 421 on which the drive signal selection circuit 200 that outputs the drive signal VOUT for driving the piezoelectric element 60 is mounted on the wiring substrate 420.

- 30 In the present embodiment, the individual lead electrode 391 and the common lead electrode 392 are formed at the same layer, but are formed to be electrically decoupled from each other. As a result, manufacturing steps can be simplified and the cost can be reduced compared with when the individual lead electrode 391 and the common lead electrode 392 are individually formed. Of course, the individual lead electrode 391 and the common lead electrode 392 may be formed at different layers.

35 A material of the individual lead electrode 391 and the common lead electrode 392 is not particularly limited as long as the material is conductive. For example, gold (Au), copper (Cu), titanium (Ti), tungsten (W), nickel (Ni), chromium (Cr), platinum (Pt), aluminum (Al), and the like may be used. In the present embodiment, gold (Au) is used as the individual lead electrode 391 and the common lead electrode 392. The individual lead electrode 391 and the common lead electrode 392 may have an adhesion layer for improving the adhesion with the first electrode 360, the second electrode 380, and the vibration plate 350.

- 50 The individual lead electrode 391 is provided for each active portion 410, that is, for each first electrode 360. As illustrated in FIG. 16, for example, in the first pressure chamber row, the individual lead electrode 391 is coupled to the vicinity of the end portion 360b of the first electrode 360 provided on the outside of the piezoelectric body 370 via the wiring portion 385, and is drawn out in the -X-axis direction to above of the pressure chamber substrate 310 and actually to above of the vibration plate 350.

55 On the other hand, as illustrated in FIG. 14, for example, in the first pressure chamber row, the common lead electrode 392 is drawn out in the -X direction from above of the second electrode 380 configuring the common electrode on the piezoelectric body 370 to above of the vibration plate 350, at both end portions in the Y-axis direction. The common lead electrode 392 has an extension portion 392a and an extension portion 392b. As illustrated in FIGS. 14 and 16, for example, in the first pressure chamber row, the

extension portion 392a extends in the Y-axis direction in a region corresponding to the end portion 312a of the pressure chamber 312, and the extension portion 392b extends in the Y-axis direction to a region corresponding to the end portion 312b of the pressure chamber 312. The extension portion 392a and the extension portion 392b are continuously provided with respect to the plurality of active portions 410 in the Y-axis direction.

The extension portion 392a and the extension portion 392b extend from the inside of the pressure chamber 312 to the outside of the pressure chamber 312 in the X-axis direction. In the present embodiment, the active portion 410 of the piezoelectric element 60 extends to the outside of the pressure chamber 312 at both end portions of the pressure chamber 312 in the X-axis direction, and the extension portion 392a and the extension portion 392b extend to the outside of the pressure chamber 312 on the active portion 410.

As illustrated in FIG. 16, the resistance wiring 401 is provided on the surface of the vibration plate 350 on the -Z-axis direction side. The resistance wiring 401 configures at least a part of the temperature detection circuit 24 that detects the temperature of the pressure chamber 312. In the present embodiment, the temperature detection circuit 24 detects a temperature by using the characteristics that an electric resistance value of a metal, a semiconductor, or the like changes depending on the temperature. A material of the resistance wiring 401 is not particularly limited as long as the material has an electric resistance value that is temperature dependent. For example, gold (Au), platinum (Pt), iridium (Ir), aluminum (Al), copper (Cu), titanium (Ti), tungsten (W), nickel (Ni), and chromium (Cr) may be used. Here, platinum (Pt) may be preferably used as a material for the resistance wiring 401 from the viewpoint that the change in resistance due to temperature is large and stability and accuracy are high. In the present embodiment, the resistance wiring 401 is provided at the same layer as the first electrode 360, and is stacked and formed on the surface of the vibration plate 350 on the -Z-axis direction side to be electrically decoupled from the first electrode 360. Therefore, a material of the resistance wiring 401 is platinum (Pt) that is the same as that of the first electrode 360. As a result, manufacturing steps can be simplified and the cost can be reduced compared with when the resistance wiring 401 is formed separately from the first electrode 360. Of course, the resistance wiring 401 may be formed at a layer different from that of the first electrode 360.

As illustrated in FIG. 14, the resistance wiring 401 is continuous, and the first end of the resistance wiring 401 on the +X-axis direction side in the X-axis direction is coupled to the measurement lead electrode 393a, and the second end of the resistance wiring 401 on the -X-axis direction side in the X-axis direction is coupled to the measurement lead electrode 393b. The measurement lead electrodes 393a and 393b are electrically coupled to the wiring substrate 420. As a result, the resistance wiring 401 is electrically coupled to the temperature information output circuit 26, and the temperature information output circuit 26 can measure an electric resistance value of the resistance wiring 401. In the present embodiment, the resistance wiring 401 is covered with the piezoelectric body 370, and is located between the vibration plate 350 and the piezoelectric body 370 in the Z-axis direction.

The resistance wiring 401 includes a first pressure chamber row side meandering pattern on the +X-axis direction side in the X-axis direction and a second pressure chamber row side meandering pattern on the -X-axis direction side in

the X-axis direction. The first pressure chamber row side meandering pattern meanders in the Y-axis direction at a position overlapping the supply communication path 319 communicating with each pressure chamber 312 configuring the first pressure chamber row when viewed from the -Z-axis direction. The second pressure chamber row side meandering pattern meanders in the Y-axis direction at a position overlapping the supply communication path 319 communicating with each pressure chamber 312 configuring the second pressure chamber row when viewed from the -Z-axis direction. That is, the resistance wiring 401 has the first pressure chamber row side meandering pattern corresponding to the first pressure chamber row formed by the plurality of pressure chambers 312 and the second pressure chamber row side meandering pattern corresponding to the second pressure chamber row formed by the plurality of pressure chambers 312. As illustrated in FIGS. 15 and 16, a distance between the end portion of the pressure chamber 312 on the -Z-axis direction side and the resistance wiring 401 in the Z-axis direction is smaller than a dimension of the pressure chamber 312 in the Z-axis direction. For example, in the first pressure chamber row, the longest distance in the X-axis direction between the end portion 312a of the pressure chamber 312 in the +X direction and the resistance wiring 401 is smaller than the dimension of the pressure chamber 312 in the X-axis direction. Therefore, the electric resistance value of the resistance wiring 401 is likely to change in response to a temperature change of the pressure chamber 312.

In the present embodiment, the measurement lead electrode 393 including the measurement lead electrode 393a and the measurement lead electrode 393b is formed at the same layer as the individual lead electrode 391 and the common lead electrode 392, but is electrically decoupled. As a result, manufacturing steps can be simplified and the cost can be reduced compared with when the measurement lead electrode 393 is individually formed with the individual lead electrode 391 and the common lead electrode 392. Of course, the measurement lead electrode 393 may be formed at a layer different from the individual lead electrode 391 and the common lead electrode 392.

A material of the measurement lead electrode 393 is not particularly limited as long as the material is conductive. For example, gold (Au), copper (Cu), titanium (Ti), tungsten (W), nickel (Ni), chromium (Cr), platinum (Pt), and aluminum (Al) may be used. In the present embodiment, gold (Au) is used as the measurement lead electrode 393. A material of the measurement lead electrode 393 is the same as the material of the individual lead electrode 391 and the common lead electrode 392. The measurement lead electrode 393 may have an adhesion layer that improves adhesion to the resistance wiring 401 and the vibration plate 350.

In the present embodiment, the measurement lead electrode 393 extends to be exposed in the through-hole 332 formed in the protective substrate 330, and is electrically coupled to the wiring substrate 420 in the through-hole 332. As a result, the temperature information output circuit 26 can acquire an electric resistance value of the resistance wiring 401 via the wiring substrate 420. The temperature information output circuit 26 outputs the acquired electric resistance value of the resistance wiring 401 as the temperature information signal TI in response to the temperature acquisition request signal TD from the control circuit 100. The temperature information output circuit 26 may store in advance a correspondence relationship between an electric resistance value of the resistance wiring 401 and a temperature. The temperature information output circuit 26 may

output a temperature corresponding to the electric resistance value of the resistance wiring 401 as the temperature information signal TI in response to the temperature acquisition request signal TD from the control circuit 100.

For example, when the temperature detection circuit 24 is provided outside the ejection module 22, a difference between a temperature measured by the temperature detection circuit 24 and a temperature inside the pressure chamber 312 may be larger than a difference between a temperature inside the ejection module 22 and a temperature inside the pressure chamber 312. In this case, the correction control for correcting the control signals Ctrl-H, Ctrl-C, and Ctrl-T based on the temperature information signal TI in the control circuit 100 may be reduced, and thus the optimum ejection control for the ejection module 22 suitable for the temperature of the ink in the pressure chamber 312 may not be performed. In the present embodiment, the resistance wiring 401 is provided in a stacked manner on the vibration plate 350 located inside the ejection module 22. As a result, a difference between a temperature detected based on an electric resistance value of the resistance wiring 401 that is the temperature detection circuit 24 and a temperature inside the pressure chamber 312 can be reduced, and thus the detection accuracy of a temperature of the pressure chamber 312 detected by the temperature detection circuit 24 is improved. As a result, the ejection control for the ejection module 22 suitable for a temperature of ink in the pressure chamber 312 can be performed by the control circuit 100.

That is, in the print head 20 of the present embodiment, the ejection module 22 includes the piezoelectric element 60 that includes the first electrode 360, the second electrode 380, and the piezoelectric body 370, and in which the piezoelectric body 370 is located between the first electrode 360 and the second electrode 380 in the Z-axis direction which is a stacking direction in which the first electrode 360, the second electrode 380, and the piezoelectric body 370 are stacked, and that is driven by receiving the drive signal VOUT based on the drive signal COM; the vibration plate 350 that is located on the +Z-axis direction side that is one side of the Z-axis direction that is the stacking direction with respect to the piezoelectric element 60 and is deformed by driving the piezoelectric element 60; the pressure chamber substrate 310 that is located on the +Z-axis direction side that is one side of the Z-axis direction which is the stacking direction with respect to the vibration plate 350, and is provided with a plurality of pressure chambers 312 each of which a volume changes due to deformation of the vibration plate 350; the drive signal selection circuit 200 that switches whether or not to supply the drive signal COM to the piezoelectric element 60; the wiring substrate 420 that is provided with the integrated circuit 421 including the drive signal selection circuit 200; and the resistance wiring 401 that is located on the -Z-axis direction side that is the other side of the Z-axis direction which is the stacking direction with respect to the vibration plate 350, is electrically coupled to the wiring substrate 420, and configures at least a part of the temperature detection circuit 24 that detects temperature information of the pressure chamber 312.

As a result, a difference between a temperature detected based on an electric resistance value of the resistance wiring 401 that is the temperature detection circuit 24 and a temperature inside the pressure chamber 312 can be reduced, and thus the detection accuracy of a temperature of the pressure chamber 312 detected by the temperature detection circuit 24 is improved. As a result, the ejection control for

the ejection module 22 suitable for a temperature of ink in the pressure chamber 312 can be performed by the control circuit 100.

Since at least a part of the resistance wiring 401 that is the temperature detection circuit 24 is stacked on the vibration plate 350, the resistance wiring 401 that is the temperature detection circuit 24 can be disposed closer to the pressure chamber 312, and thus the accuracy of detecting a temperature of the pressure chamber 312 detected by the temperature detection circuit 24 is further improved. As a result, the ejection control for the ejection module 22 more suitable for a temperature of ink in the pressure chamber 312 in the control circuit 100 can be performed.

6. Temperature Detection Operation

As described above, in the liquid ejection apparatus 1 of the present embodiment, the resistance wiring 401 that detects the temperature of the ejection module 22 is provided on the vibration plate 350 inside the ejection module 22 of the print head 20, and thus the resistance wiring 401 that is the temperature detection circuit 24 can be provided in the vicinity of the pressure chamber 312 in which ink is stored. As a result, a difference between a temperature detected based on an electric resistance value of the resistance wiring 401 and a temperature inside the pressure chamber 312 can be reduced, and thus the detection accuracy of a temperature of the pressure chamber 312 detected by the temperature detection circuit 24 is improved.

On the other hand, since the resistance wiring 401 that is the temperature detection circuit 24 is provided in the vicinity of the pressure chamber 312 in which the ink is stored, the following problems may occur.

From the viewpoint of improving the quality of an image formed on the medium P, several hundred or more nozzles 321 are disposed at high density in the ejection module 22. Therefore, in the ejection module 22, several hundred or more piezoelectric elements 60 corresponding to the several hundred or more nozzles 321 are disposed at high density, and thus, in the ejection module 22, signal wirings through which the drive signal VOUT supplied to the corresponding piezoelectric elements 60 propagate are disposed at high density on the vibration plate 350 in the ejection module 22. When the resistance wiring 401 is disposed on such a vibration plate 350, the resistance wiring 401 is disposed in the vicinity of the signal wiring through which the drive signal VOUT propagates, and thus noise generated due to a voltage change of the drive signal VOUT may overlap the resistance wiring 401. When noise generated due to a voltage change of the drive signal VOUT is superimposed on the resistance wiring 401, the detection accuracy of the temperature of the pressure chamber 312 detected by the temperature detection circuit 24 including the resistance wiring 401 may decrease.

When the piezoelectric element 60 is driven by the drive signal VOUT, the vibration plate 350 on which the resistance wiring 401 is stacked is displaced in association with driving of the piezoelectric element 60. As a result, the impedance of the resistance wiring 401 changes, and thus the detection accuracy of the temperature of the pressure chamber 312 detected by the temperature detection circuit 24 including the resistance wiring 401 decreases.

As described above, the ejection module 22 changes the volume of the pressure chamber 312 due to deformation or vibration of the vibration plate 350 caused by driving the piezoelectric element 60, so that pressure is applied to the ink in the pressure chamber 312, and thus the ink is ejected from the nozzle 321. In the ejection module 22 having such a structure, the temperature of the ink stored in the pressure

chamber 312 may change momentarily due to a change in the pressure of the pressure chamber 312 generated when the ink is ejected. Thus, the detection accuracy of the normal temperature of the pressure chamber 312 detected by the temperature detection circuit 24 including the resistance wiring 401 may decrease.

In order to solve the problem, in the liquid ejection apparatus 1 of the present embodiment, the temperature information signal TI corresponding to the temperature detection information TH detected by the temperature detection circuit 24 including the resistance wiring 401 is input to the control circuit 100 in the period in which a voltage value of at least one of the drive signal COMA output by the drive circuit 50a and the drive signal COMB output by the drive circuit 50b is constant, and, preferably, the temperature information signal TI corresponding to the temperature detection information TH detected by the temperature detection circuit 24 including the resistance wiring 401 is input to the control circuit 100 in the period in which a voltage value of the drive signal COMA output by the drive circuit 50a is constant and a voltage value of the drive signal COMB output by the drive circuit 50b is constant. In other words, the print head 20 outputs the temperature information signal TI corresponding to the temperature detection information TH detected by the temperature detection circuit 24 including the resistance wiring 401 in the period in which a voltage value of at least one of the input drive signal COMA and drive signal COMB is constant, and, preferably, outputs the temperature information signal TI corresponding to the temperature detection information TH detected by the temperature detection circuit 24 including the resistance wiring 401 in the period in which a voltage value of the input drive signal COMA is constant and a voltage value of the input drive signal COMB is constant.

As a result, a probability that a voltage value of the drive signal VOUT varies is reduced and a probability that noise is superimposed on the temperature detection information TH due to the variation in the voltage value of the drive signal VOUT is reduced at a timing at which the temperature detection circuit 24 including the resistance wiring 401 detects the temperature detection information TH included in the temperature information signal TI input to the control circuit 100 and the temperature detection information TH included in the temperature information signal TI output by the print head 20. In the period in which the temperature detection circuit 24 including the resistance wiring 401 detects the temperature detection information TH, a voltage value of the drive signal VOUT does not vary and the piezoelectric element 60 is held at a constant displacement. Therefore, a probability that the impedance of the resistance wiring 401 changes during the detection period is reduced, and a probability that the temperature of the ink stored in the pressure chamber 312 changes momentarily is also reduced. As a result, even when the resistance wiring 401 that is the temperature detection circuit 24 is provided in the vicinity of the pressure chamber 312 in which the ink is stored, a probability that the detection accuracy of the temperature of the pressure chamber 312 detected by the temperature detection circuit 24 including the resistance wiring 401 is reduced is reduced, and thus the temperature detection circuit 24 can detect the temperature of the pressure chamber 312 with high accuracy.

In the liquid ejection apparatus 1 that operates as described above, a specific example of an acquisition timing of acquiring the temperature of the ejection module 22 will be described. FIG. 18 is a diagram illustrating an example of an acquisition timing of acquiring the temperature of the

ejection module 22 included in the print head 20. In describing an acquisition timing of acquiring the temperature of the ejection module 22, first, an operation of the liquid ejection apparatus 1 will be described, and based on the operation, a specific example of an acquisition timing of the temperature of the pressure chamber 312 of the ejection module 22 will be described.

As illustrated in FIG. 18, a power supply voltage is supplied to the liquid ejection apparatus 1 at time point t10. 10 As a result, the liquid ejection apparatus 1 is started. When the liquid ejection apparatus 1 is started, the drive circuit 50a starts outputting a signal of which a voltage value is constant at a voltage Vb as the drive signal COMA, and the drive circuit 50b starts outputting a signal of which a voltage value is constant at the voltage Vb as the drive signal COMB. 15 Here, the voltage Vb preferably has the same voltage value as that of the reference voltage signal VBS.

After each of the drive circuits 50a and 50b starts outputting a signal having a constant voltage value as the drive 20 signals COMA and COMB at the voltage Vb, the control circuit 100 outputs the head control signal DI in which one of the selection signal Sa or the selection signal Sb is set to an H level. As a result, a voltage value of the first electrode 360 of the piezoelectric element 60 becomes a voltage value 25 of one of the drive signals COMA and COMB. Thereafter, voltage values of the drive signals COMA and COMB output by the respective drive circuits 50a and 50b become constant at the voltage Vb, so that a voltage value of the first electrode 360 of the piezoelectric element 60 is the same 30 voltage Vb as that of the reference voltage signal VBS.

After the voltage value of the first electrode 360 of the piezoelectric element 60 is constant at the voltage Vb, the control circuit 100 outputs the head control signal DI in which both the selection signal Sa and the selection signal 35 Sb are set to an L level. As a result, the selection circuit 230 is controlled to be non-conductive, and the voltage value of the first electrode 360 of the piezoelectric element 60 is held at the voltage Vb. Thereafter, the liquid ejection apparatus 1 waits in a period until an image information signal is input 40 from an external apparatus in a state in which the drive circuit 50a continues to output a signal of which a voltage value is constant to be the voltage Vb as the drive signal COMA, and the drive circuit 50b continues to output a signal of which a voltage value is constant to be the voltage 45 Vb as the drive signal COMB.

In the standby period in which the liquid ejection apparatus 1 waits for input of the image information signal from the external apparatus, the drive circuit 50b outputs a signal including a micro-vibration waveform obs as the drive signal COMB at predetermined intervals. In this case, the control circuit 100 outputs the head control signal DI in which the selection signal Sb is set to an H level. As a result, the micro-vibration is executed at predetermined intervals in the standby period. As a result, the probability that the ink sticks to the vicinity of the nozzle 321 during the standby 55 period is reduced, and the probability that the ink viscosity in the vicinity of the nozzle 321 increases is also reduced. Here, the micro-vibration waveform obs output by the drive circuit 50b is a signal waveform different from the trapezoidal waveform Bdp2 described above.

At time point t20, when an image information signal is input from the external apparatus, the drive circuit 50a starts outputting a signal of which a voltage value is constant at the voltage Vc as the drive signal COMA, and the drive circuit 50b starts outputting a signal of which a voltage value is constant at the voltage Vc as the drive signal COMB. After the respective drive circuits 50a and 50b start outputting

starts outputting the signals of which a voltage value is constant at the voltage V_c as the drive signals COMA and COMB, the control circuit **100** outputs head control signal DI in which one of the selection signal S_a or the selection signal S_b is set to an H level. As a result, a voltage value of the first electrode **360** of the piezoelectric element **60** becomes a voltage value of one of the drive signals COMA and COMB. Thereafter, the voltage values of the drive signals COMA and COMB output by the respective drive circuits **50a** and **50b** are constant at the voltage V_c , so that a voltage value of the first electrode **360** of the piezoelectric element **60** becomes the voltage V_c . After the voltage value of the first electrode **360** of the piezoelectric element **60** is constant at the voltage V_c , the control circuit **100** outputs the head control signal DI in which both the selection signal S_a and the selection signal S_b are set to an L level. As a result, the selection circuit **230** is controlled to be non-conductive, and the voltage value of the first electrode **360** of the piezoelectric element **60** is held by the voltage V_c .

At time point t_{30} after the voltage values of the drive signals COMA and COMB output by the drive circuits **50a** and **50b** are constant at the voltage V_c , the control circuit **100** outputs the control signal Ctrl-C for moving the carriage **21** on which the print head **20** is mounted in the forward direction F_w along the scanning axis. As a result, the carriage **21** starts to be moved in the forward direction F_w along the scanning axis.

At time point t_{40} after the carriage **21** starts to be moved in the forward direction F_w along the scanning axis, the drive circuit **50a** starts outputting a signal in which the trapezoidal waveform $Adp1$ and the trapezoidal waveform $Adp2$ are continuous as the drive signal COMA, and the drive circuit **50b** starts outputting a signal in which the trapezoidal waveform $Bdp1$ and the trapezoidal waveform $Bdp2$ are continuous as the drive signal COMB. At the subsequent time point t_{50} , when a scanning position of the carriage **21** on which the print head **20** is mounted reaches a printing region for forming an image on the medium P , the control circuit **100** outputs the head control signal DI corresponding to the image information signal input from the external apparatus. Consequently, the selection control circuit **210** outputs the selection signals S_a and S_b with logic levels corresponding to the head control signal DI, and the selection circuit **230** outputs the drive signals V_{OUT} based on the drive signals COMA and COMB. As a result, a desired image is formed on the medium P . That is, a printing process is performed.

Here, the printing region includes a region in which the print head **20** can eject ink to the medium P , and includes at least a region in which the print head **20** and the medium P are located to face each other.

At time point t_{60} , the printing process in the forward direction F_w along the scanning axis is completed. When the printing process in the forward direction F_w is completed, the control circuit **100** outputs the selection signals S_a and S_b for controlling the selection circuit **230** to be non-conductive. As a result, a voltage value of the first electrode **360** of the piezoelectric element **60** is held at the voltage V_c . Thereafter, at time point t_{70} , the drive circuit **50a** stops outputting the drive signal COMA including the trapezoidal waveforms $Adp1$ and $Adp2$, and starts outputting a signal of which a voltage value is constant at the voltage V_c as the drive signal COMA, and the drive circuit **50b** stops outputting the drive signal COMB including the trapezoidal waveforms $Bdp1$ and $Bdp2$, and starts outputting a signal of which a voltage value is constant at the voltage V_c as the drive signal COMB.

When a scanning position of the carriage **21** reaches a stop region at time point t_{80} after the voltage values of the drive signals COMA and COMB become constant at the voltage V_c in the respective drive circuits **50a** and **50b**, the control circuit **100** outputs the control signal Ctrl-C for stopping the carriage **21** on which the print head **20** is mounted. As a result, the carriage **21** is stopped.

At time point t_{90} after the carriage **21** is stopped, the drive circuit **50a** starts outputting a signal of which a voltage value is constant at the voltage V_b as the drive signal COMA, and the drive circuit **50b** starts outputting a signal of which a voltage value is constant at the voltage V_b as the drive signal COMB. After the respective drive circuits **50a** and **50b** start outputting the signals of which the voltage values are constant at the voltage V_b as the drive signals COMA and COMB, the control circuit **100** outputs the head control signal DI in which one of the selection signal S_a or the selection signal S_b is set to an H level. As a result, a voltage value of the first electrode **360** of the piezoelectric element **60** becomes a voltage value of one of the drive signals COMA and COMB.

After the voltage value of the first electrode **360** of the piezoelectric element **60** becomes constant at the voltage V_b , the control circuit **100** outputs the head control signal DI in which both the selection signal S_a and the selection signal S_b are set to an L level. As a result, the selection circuit **230** is controlled to be non-conductive, and the voltage value of the first electrode **360** of the piezoelectric element **60** is held at the voltage V_b . Thereafter, the liquid ejection apparatus **1** waits in a period until the reversing process of the carriage **21** in the scanning direction is completed in a state in which the drive circuit **50a** continues to output a signal of which a voltage value is constant to be the voltage V_b as the drive signal COMA, and the drive circuit **50b** continues to output a signal of which a voltage value is constant to be the voltage V_b as the drive signal COMB.

In the standby period until the reversing process of the scanning position of the carriage **21** is completed, the drive circuit **50b** outputs a signal including the micro-vibration waveform obs as the drive signal COMB at predetermined intervals. In this case, the control circuit **100** outputs the head control signal DI in which the selection signal S_b is set to an H level. As a result, the micro-vibration is executed at predetermined intervals in the standby period. As a result, the probability that the ink sticks to the vicinity of the nozzle **321** during the standby period is reduced, and the probability that the ink viscosity in the vicinity of the nozzle **321** increases is also reduced.

At time point t_{100} , when the reversing process of the carriage **21** in the scanning direction is completed, the drive circuit **50a** starts outputting a signal of which a voltage value is constant at the voltage V_c as the drive signal COMA, and the drive circuit **50b** starts outputting a signal of which a voltage value is constant at the voltage V_c as the drive signal COMB. After the respective drive circuits **50a** and **50b** start outputting starts outputting the signals of which a voltage value is constant at the voltage V_c as the drive signals COMA and COMB, the control circuit **100** outputs head control signal DI in which one of the selection signal S_a or the selection signal S_b is set to an H level. As a result, a voltage value of the first electrode **360** of the piezoelectric element **60** becomes a voltage value of one of the drive signals COMA and COMB. Thereafter, the voltage values of the drive signals COMA and COMB output by the respective drive circuits **50a** and **50b** are constant at the voltage V_c , so that a voltage value of the first electrode **360** of the piezoelectric element **60** becomes the voltage V_c . After the

voltage value of the first electrode 360 of the piezoelectric element 60 is constant at the voltage Vc, the control circuit 100 outputs the head control signal DI in which both the selection signal Sa and the selection signal Sb are set to an L level. As a result, the selection circuit 230 is controlled to be non-conductive, and the voltage value of the first electrode 360 of the piezoelectric element 60 is held by the voltage Vc.

At time point t110 after the voltage values of the drive signals COMA and COMB output by the respective drive circuits 50a and 50b are constant at the voltage Vc, the control circuit 100 outputs the control signal Ctrl-C for moving the carriage 21 on which the print head 20 is mounted in the reverse direction Rv along the scanning axis. As a result, the carriage 21 starts to be moved in the reverse direction Rv along the scanning axis.

At time point t120 after the carriage 21 starts to be moved in the reverse direction Rv along the scanning axis, the drive circuit 50a starts outputting a signal in which the trapezoidal waveform Adp1 and the trapezoidal waveform Adp2 are continuous as the drive signal COMA, and the drive circuit 50b starts outputting a signal in which the trapezoidal waveform Bdp1 and the trapezoidal waveform Bdp2 are continuous as the drive signal COMB. At the subsequent time point t130, when a scanning position of the carriage 21 on which the print head 20 is mounted reaches a printing region for forming an image on the medium P, the control circuit 100 outputs the head control signal DI corresponding to the image information signal input from the external apparatus. Consequently, the selection control circuit 210 outputs the selection signals Sa and Sb with logic levels corresponding to the head control signal DI, and the selection circuit 230 outputs the drive signals VOUT based on the drive signals COMA and COMB. As a result, a desired image is formed on the medium P. That is, the printing process is performed again.

Here, in the period from time point t10 to time point t20 illustrated in FIG. 18, the liquid ejection apparatus 1 waits for input of an image information signal from the external apparatus. Such an operation mode in which the liquid ejection apparatus 1 waits for input of an image information signal from the external apparatus may be referred to as a printing process standby mode. In the period from time point t20 to time point t90 illustrated in FIG. 18, the liquid ejection apparatus 1 executes a printing process based on the image information. Such an operation mode in which the liquid ejection apparatus 1 executes the printing process may be referred to as a printing process mode. In the period from time point t90 to time point t100 illustrated in FIG. 18, the liquid ejection apparatus 1 waits until the reversing process of the carriage 21 in the scanning direction is completed. Such an operation mode of waiting for the reversing process of the carriage 21 in the scanning direction is referred to as a reversing process standby mode.

Here, the same processing is executed except that the scanning direction of the carriage 21 is different between time point t20 and time point t100 illustrated in FIG. 18, the same processing is executed except that the scanning direction of the carriage 21 is different between time point t30 and time point t110, the same processing is executed except that the scanning direction of the carriage 21 is different between time point t40 and time point t120, and the same processing is executed except that the scanning direction of the carriage 21 is different between time point t50 and time point t130. That is, the liquid ejection apparatus 1 repeatedly executes the processing from time point t20 to time point t90 while reversing an operation direction of the carriage 21, to form

a desired image on the medium P. In other words, the liquid ejection apparatus 1 forms a desired image on the medium P by repeating the printing process mode and the reversing process standby mode.

5 In the liquid ejection apparatus 1 configured as described above, a specific example of an acquisition timing of the temperature of the pressure chamber 312 included in the ejection module 22 will be described. In the liquid ejection apparatus 1 of the present embodiment, the temperature of 10 the pressure chamber 312 included in the ejection module 22 is acquired in at least one of detection periods Tdet1 to Tdet6 illustrated in FIG. 18. Here, as illustrated in FIG. 18, the detection periods Tdet3 and Tdet4 are periods in the printing process mode, and the detection periods Tdet5 and Tdet6 are 15 periods in the reversing process standby mode. That is, the detection periods Tdet3, Tdet4, Tdet5, and Tdet6, which are acquisition timings of the temperature of the pressure chamber 312 of the ejection module 22, are generated a plurality of times during a period during which the liquid ejection 20 apparatus 1 forms a desired image on the medium P.

The detection period Tdet1 is a period in the printing process standby mode, and is a period that is started when a predetermined period Δt elapses after a state in which the voltage values of the drive signals COMA and COMB 25 output by the respective drive circuits 50a and 50b vary is turned to a state in which the voltage values are constant at the voltage Vb at time point t10, and is ended when the drive circuit 50b starts outputting a signal including the micro-vibration waveform obs as the drive signal COMB. That is, 30 in the detection period Tdet1, the drive circuit 50a outputs a signal of which a voltage value is constant at the voltage Vb as the drive signal COMA, and the drive circuit 50b outputs a signal of which a voltage value is constant at the voltage Vb as the drive signal COMB. The detection period 35 Tdet1 is a period in the printing process standby mode, and thus, in the detection period Tdet1, the carriage 21 is stopped. That is, the detection period Tdet1 is also a period in which the carriage is stopped.

The detection period Tdet2 is a period in the printing 40 process standby mode, and is a period which is started when the predetermined period Δt elapses after a state in which the voltage value of the drive signal COMB varies is turned to a state in which the voltage value is constant by ending the output of the signal including the micro-vibration waveform obs as the drive signal COMB and is ended at time point t20 45 at which an image information signal is input from the external apparatus. In this detection period Tdet2, the drive circuit 50a outputs a signal of which a voltage value is constant at the voltage Vb as the drive signal COMA, and the drive circuit 50b outputs a signal of which a voltage value is constant at the voltage Vb as the drive signal COMB. The detection period Tdet2 is a period in the printing process standby mode, and thus, in the detection period Tdet2, the carriage 21 is stopped. That is, the detection 50 period Tdet2 is also a period in which the carriage is stopped.

The detection period Tdet3 is a period in the printing process mode, and is a period that is started when the predetermined period Δt elapses after a state in which the voltage values of the drive signals COMA and COMB 60 output by the respective drive circuits 50a and 50b vary is turned to a state in which the voltage values are constant at the voltage Vc at time point t20, and is ended at time point t40 at which the drive circuit 50a starts outputting the drive signal COMA including the trapezoidal waveforms Adp1 and Adp2 and the drive circuit 50b starts outputting the drive signal COMB including the trapezoidal waveforms Bdp1 65 and Bdp2.

and $Bdp2$. That is, in the detection period $Tdet3$, the drive circuit $50a$ outputs a signal of which a voltage value is constant at the voltage Vc as the drive signal $COMA$, and the drive circuit $50b$ outputs a signal of which a voltage value is constant at the voltage Vc as the drive signal $COMB$.

The detection period $Tdet4$ is a period in the printing process mode, and is a period that is started when the predetermined period Δt elapses after a state in which the voltage values of the drive signals $COMA$ and $COMB$ output by the respective drive circuits $50a$ and $50b$ vary is turned to a state in which the voltage values are constant at the voltage Vc at time point $t70$, and is ended at time point $t90$ immediately before the voltage values of the drive signals $COMA$ and $COMB$ change to the voltage Vb . That is, in the detection period $Tdet4$, the drive circuit $50a$ outputs a signal of which a voltage value is constant at the voltage Vc as the drive signal $COMA$, and the drive circuit $50b$ outputs a signal of which a voltage value is constant at the voltage Vc as the drive signal $COMB$.

The detection period $Tdet5$ is a period in the reversing process standby mode, and is a period that is started when the predetermined period Δt elapses after a state in which the voltage values of the drive signals $COMA$ and $COMB$ output by the respective drive circuits $50a$ and $50b$ vary is turned to a state in which the voltage values are constant at the voltage Vb at time point $t90$, and is ended when the drive circuit $50b$ starts outputting a signal including the micro-vibration waveform obs as the drive signal $COMB$. That is, in the detection period $Tdet5$, the drive circuit $50a$ outputs a signal of which a voltage value is constant at the voltage Vb as the drive signal $COMA$, and the drive circuit $50b$ outputs a signal of which a voltage value is constant at the voltage Vb as the drive signal $COMB$. The detection period $Tdet5$ is a period in the reversing process standby mode, and thus, in the detection period $Tdet5$, the carriage 21 is stopped. That is, the detection period $Tdet5$ is also a period in which the carriage is stopped.

The detection period $Tdet6$ is a period in the reversing process standby mode, and is a period which is started when the predetermined period Δt elapses after a state in which the voltage value of the drive signal $COMB$ varies is turned to a state in which the voltage value is constant by ending the output of the signal including the micro-vibration waveform obs as the drive signal $COMB$ and is ended at time point $t100$ at which the reversing process is completed. In this detection period $Tdet6$, the drive circuit $50a$ outputs a signal of which a voltage value is constant at the voltage Vb as the drive signal $COMA$, and the drive circuit $50b$ outputs a signal of which a voltage value is constant at the voltage Vb as the drive signal $COMB$. The detection period $Tdet6$ is a period in the reversing process standby mode, and thus in the detection period $Tdet6$, the carriage 21 is stopped. That is, the detection period $Tdet2$ is also a period in which the carriage is stopped.

In each of such detection periods $Tdet1$ to $Tdet6$, the temperature information signal TI corresponding to the temperature detection information TH detected by the temperature detection circuit 24 including the resistance wiring 401 is input to the control circuit 100 , and the print head 20 outputs the temperature information signal TI corresponding to the temperature detection information TH detected by the temperature detection circuit 24 including the resistance wiring 401 . Therefore, a probability that a voltage value of the drive signal $VOUT$ varies at the timing of detection by the temperature detection circuit 24 including the resistance wiring 401 is reduced, a probability that noise is superimposed on the temperature detection information TH due to

the variation in the voltage value of the drive signal $VOUT$ is reduced, and a voltage value the drive signal $VOUT$ does not vary and the piezoelectric element 60 is held at a constant displacement. As a result, a probability that the impedance of the resistor wiring 401 changes during the detection period is reduced, and a probability that the temperature of the ink stored in the pressure chamber 312 changes momentarily is also reduced. As a result, even when the resistance wiring 401 that is the temperature detection circuit 24 is provided in the vicinity of the pressure chamber 312 in which the ink is stored, a probability that the detection accuracy of the temperature of the pressure chamber 312 detected by the temperature detection circuit 24 including the resistance wiring 401 is reduced is reduced, and thus the temperature detection circuit 24 can detect the temperature of the pressure chamber 312 with high accuracy.

In each of the detection periods $Tdet1$ to $Tdet6$, the temperature information signal TI corresponding to the temperature detection information TH detected by the temperature detection circuit 24 including the resistor wiring 401 is input to the control circuit 100 , and the print head 20 outputs the temperature information signal TI corresponding to the temperature detection information TH detected by the temperature detection circuit 24 including the resistance wiring 401 . Therefore, even in a case where a state in which the voltage values of the drive signals $COMA$ and $COMB$ vary is turned to a state in which the voltage values are constant, even when voltage vibration occurs in the drive signals $COMA$ and $COMB$, the influence of the voltage vibration is alleviated due to the predetermined period Δt . As a result, even when the resistance wiring 401 that is the temperature detection circuit 24 is provided in the vicinity of the pressure chamber 312 in which the ink is stored, a probability that the detection accuracy of the temperature of the pressure chamber 312 detected by the temperature detection circuit 24 is reduced is further reduced, and the temperature detection circuit 24 can detect the temperature of the pressure chamber 312 with higher accuracy.

The carriage 21 is stopped during the detection periods $Tdet1$, $Tdet2$, $Tdet5$, and $Tdet6$. As a result, a probability that noise generated due to sliding of a cable caused by the movement of the carriage 21 or the vibration of the carriage 21 is superimposed on the temperature detection information TH corresponding to the temperature of the pressure chamber 312 detected by the temperature detection circuit 24 is reduced. As a result, even when the resistance wiring 401 that is the temperature detection circuit 24 is provided in the vicinity of the pressure chamber 312 in which the ink is stored, a probability that the detection accuracy of the temperature of the pressure chamber 312 detected by the temperature detection circuit 24 is reduced is further reduced, and the temperature detection circuit 24 can detect the temperature of the pressure chamber 312 with higher accuracy.

Here, the control signal $Ctrl-H$ output by the control circuit 100 is an example of a control signal, one of the drive circuits $50a$ and $50b$ is an example of a first drive signal output circuit, and the other of the drive circuits $50a$ and $50b$ is an example of a second drive signal output circuit. One of the drive signals $COMA$ and $COMB$ output by one of the drive circuits $50a$ and $50b$ corresponding to the first drive signal output circuit is an example of a first drive signal, and the other of the drive signals $COMA$ and $COMB$ output by the other of the drive circuits $50a$ and $50b$ corresponding to the second drive signal output circuit is an example of a second drive signal. Here, in view of the fact that the trapezoidal waveforms $Adp1$, $Adp2$, $Bdp1$, and $Bdp2$

included in the drive signals COMA and COMB are supplied to the piezoelectric element 60, the trapezoidal waveforms Adp1, Adp2, Bdp1, and Bdp2 included in one of the drive signals COMA and COMB output by one of the drive circuits 50a and 50b corresponding to the first drive signal output circuit are an example of the first drive signal, and the trapezoidal waveforms Adp1, Adp2, Bdp1, and Bdp2 included in the other of the drive signals COMA and COMB output by the other of the drive circuits 50a and 50b corresponding to the second drive signal output circuit are an example of the second drive signal. The Z-axis direction is an example of a stacking direction, the +Z-axis direction side of the Z-axis direction that is the stacking direction is an example of one side of the stacking direction, and the -Z-axis direction side of the Z-axis direction that is the stacking direction is an example of the other side of the stacking direction. The selection circuit 230 is an example of a switch circuit. The temperature detection circuit 24 is an example of a temperature detection portion, and the temperature detection information TH output by the temperature detection circuit 24 is an example of temperature information.

7. Action and Effect

As described above, in the liquid ejection apparatus 1 of the present embodiment, the temperature information signal TI corresponding to the temperature detection information TH detected by the temperature detection circuit 24 including the resistor wiring 401 is input to the control circuit 100 in a period in which voltage values of the drive signals COMA and COMB are constant. That is, the print head 20 of the present embodiment outputs the temperature information signal TI based on the temperature detection information TH detected by the temperature detection circuit 24 including the resistor wiring 401 in a period in which the voltage values of the input drive signals COMA and COMB are constant. As a result, a probability that the voltage value of the drive signal VOUT varies at the timing at which the temperature detection circuit 24 including the resistor wiring 401 detects the temperature of the pressure chamber 312 is reduced, a probability that noise is superimposed on the temperature detection information TH due to a variation in a voltage value of the drive signal VOUT is reduced, and the voltage value of the drive signal VOUT does not vary and the piezoelectric element 60 is held at a constant displacement. Therefore, a probability that the impedance of the resistor wiring 401 changes during the detection period is reduced, and a probability that the temperature of the ink stored in the pressure chamber 312 changes momentarily is also reduced. As a result, even when the resistance wiring 401 that is the temperature detection circuit 24 is provided in the vicinity of the pressure chamber 312 in which the ink is stored, a probability that the detection accuracy of the temperature of the pressure chamber 312 detected by the temperature detection circuit 24 including the resistor wiring 401 is reduced is reduced, and thus the temperature detection circuit 24 can detect the temperature of the pressure chamber 312 with high accuracy.

In the period in which a state in which the voltage values of the drive signals COMA and COMB output by the drive circuits 50a and 50b vary is turned to a state in which the voltage values are constant, the temperature information signal TI corresponding to the temperature detection information TH detected by the temperature detection circuit 24 including the resistor wiring 401 is input to the control circuit 100, and the print head 20 outputs the temperature information signal TI corresponding to the temperature detection information TH detected by the temperature detection circuit 24 including the resistor wiring 401.

tion circuit 24 including the resistor wiring 401. As a result, in a case where a state in which the voltage values of the drive signals COMA and COMB vary is turned to a state in which the voltage values are constant, even when voltage vibration occurs in the drive signals COMA and COMB, the influence of the voltage vibration is alleviated due to the predetermined period Δt . As a result, even when the resistance wiring 401 that is the temperature detection circuit 24 is provided in the vicinity of the pressure chamber 312 in which the ink is stored, a probability that the detection accuracy of the temperature of the pressure chamber 312 detected by the temperature detection circuit 24 is reduced is further reduced, and the temperature detection circuit 24 can detect the temperature of the pressure chamber 312 with higher accuracy.

In the liquid ejection apparatus 1 of the present embodiment, in the period in which the voltage values of the drive signals COMA and COMB are constant and the carriage is stopped, the temperature information signal TI corresponding to the temperature detection information TH detected by the temperature detection circuit 24 including the resistor wiring 401 is input to the control circuit 100, and the print head 20 outputs the temperature information signal TI corresponding to the temperature detection information TH detected by the temperature detection circuit 24 including the resistor wiring 401. As a result, a probability that noise generated due to sliding of a cable caused by the movement of the carriage 21 or the vibration of the carriage 21 is superimposed on the temperature detection information TH corresponding to the temperature of the pressure chamber 312 detected by the temperature detection circuit 24 is reduced. As a result, even when the resistance wiring 401 that is the temperature detection circuit 24 is provided in the vicinity of the pressure chamber 312 in which the ink is stored, a probability that the detection accuracy of the temperature of the pressure chamber 312 detected by the temperature detection circuit 24 is reduced is further reduced, and the temperature detection circuit 24 can detect the temperature of the pressure chamber 312 with higher accuracy.

In the liquid ejection apparatus 1 of the present embodiment, a probability that the voltage value of the drive signal VOUT varies at the timing at which the temperature detection circuit 24 including the resistor wiring 401 detects the temperature of the pressure chamber 312 can be reduced. Therefore, a more remarkable effect is achieved by using, as the liquid ejection apparatus 1, a large-format printer that ejects ink on the medium P having a short side width or more of A3 in which a wiring length of a wiring through which the drive signals COMA and COMB propagate can be increased.

Although embodiments and modification examples have been described above, the present disclosure is not limited to these embodiments, and can be implemented in various aspects without departing from the concept thereof. For example, the above embodiments can be combined as appropriate.

The present disclosure includes a configuration substantially the same as the configuration described in the embodiments (for example, a configuration having the same function, method, and result, or a configuration having the same object and effect). The present disclosure also includes a configuration in which a non-essential portion of the configuration described in the embodiment is replaced. The present disclosure includes a configuration that achieves the same action effects as the configuration described in the embodiment or a configuration that can achieve the same

object. The present disclosure includes a configuration in which a well-known technique is added to the configuration described in the embodiment.

The following contents are derived from the above-described embodiments.

According to an aspect of the present disclosure, there is provided a liquid ejection apparatus including a control circuit that outputs a control signal; a first drive signal output circuit that outputs a first drive signal; and a print head that receives the control signal and the first drive signal and ejects a liquid, in which the print head includes

a piezoelectric element that includes a first electrode, a second electrode, and a piezoelectric body and in which the piezoelectric body is located between the first electrode and the second electrode in a stacking direction in which the first electrode, the second electrode, and the piezoelectric body are stacked, and that is driven by receiving the first drive signal, a vibration plate that is located on one side of the stacking direction with respect to the piezoelectric element and is deformed by driving the piezoelectric element, a pressure chamber substrate that is located on the one side of the stacking direction with respect to the vibration plate and is provided with a plurality of pressure chambers of which volumes change due to deformation of the vibration plate, a switch circuit that switches whether or not to supply the first drive signal to the piezoelectric element, a wiring substrate that is provided with the switch circuit, and a temperature detection portion that is located on the other side of the stacking direction with respect to the vibration plate, is electrically coupled to the wiring substrate, and detects temperature information of the pressure chamber, and the temperature information detected by the temperature detection portion in a period in which a voltage value of the first drive signal is constant is input to the control circuit.

According to this liquid ejection apparatus, since the temperature detection portion is provided inside the print head, it is possible to accurately detect the temperature information of the pressure chamber. However, since the temperature detection portion is provided inside the print head, the first drive signal for driving the print head may interfere with the temperature information of the pressure chamber detected by the temperature detection portion. In order to solve such a problem, according to the liquid ejection apparatus, the temperature detection portion detects the temperature information of the pressure chamber input to the control circuit in a period in which the voltage value of the first drive signal is constant. Consequently, when the temperature detection portion acquires the temperature information of the pressure chamber input to the control circuit, the probability that the first drive signal interferes with the temperature information of the pressure chamber is reduced. As a result, the acquisition accuracy of the temperature information of the pressure chamber input to the control circuit is improved, and the stability of the operation of the control circuit based on the temperature information is improved.

According to this liquid ejection apparatus, the temperature information of the pressure chamber input to the control circuit is detected by the temperature detection portion in the period in which a voltage value of the first drive signal is

constant. Thus, the vibration plate is not deformed and the internal pressure of the pressure chamber does not change in the period in which the temperature information of the pressure chamber input to the control circuit is detected. As a result, a probability that noise generated by the deformation of the vibration plate is superimposed on the temperature information of the pressure chamber input to the control circuit is reduced, and a probability that the temperature in the pressure chamber rises momentarily due to the change in the internal pressure of the pressure chamber when the temperature information of the pressure chamber input to the control circuit is detected is also reduced. As a result, the acquisition accuracy of the temperature information of the pressure chamber input to the control circuit is improved, and the stability of an operation of the control circuit based on the temperature information is improved.

In the aspect of the liquid ejection apparatus, at least a part of the temperature detection portion may be stacked on the vibration plate.

According to this liquid ejection apparatus, the temperature detection portion can be disposed closer to the pressure chamber, and the accuracy of detecting the temperature of the pressure chamber in the temperature detection portion is further improved.

In the aspect of the liquid ejection apparatus, the liquid ejection apparatus may further include a second drive signal output circuit that outputs a second drive signal, in which the print head may receive the first drive signal and the second drive signal and ejects the liquid, the piezoelectric element may be driven by receiving the first drive signal or the second drive signal, and the temperature information detected by the temperature detection portion may be input to the control circuit in a period in which the voltage value of the first drive signal is constant and a voltage value of the second drive signal is constant.

According to this liquid ejection apparatus, even in a configuration in which multi-gradation is realized in a short cycle when the piezoelectric element is driven by receiving a plurality of drive signals, the temperature information of the pressure chamber input to the control circuit is detected by the temperature detection portion in the period in which the voltage value of the first drive signal is constant and the voltage value of the second drive signal is constant. Therefore, a probability that the first drive signal and the second drive signal interfere with the temperature information of the pressure chamber is reduced, a probability that noise generated due to deformation of the vibration plate is superimposed is reduced, and the temperature in the pressure chamber rises momentarily due to the change in the internal pressure of the pressure chamber is also reduced. As a result, the acquisition accuracy of the temperature information of the pressure chamber input to the control circuit is improved, and the stability of an operation of the control circuit based on the temperature information is improved.

In the aspect of the liquid ejection apparatus, the liquid ejection apparatus may be a large-format printer that ejects the liquid on a medium having a short side width or more of A3.

According to this liquid ejection apparatus, the temperature information of the pressure chamber input to the control circuit is detected by the temperature detection portion in the period in which the voltage value of the first drive signal is constant. Therefore, even when overshoot or undershoot occurs in the first drive signal, a probability that the first drive signal and the second drive signal interfere with the

temperature information of the pressure chamber is reduced, a probability that noise generated due to deformation of the vibration plate is superimposed is reduced, and the temperature in the pressure chamber rises momentarily due to the change in the internal pressure of the pressure chamber is also reduced. Thus, even when the liquid ejection apparatus 1 is a large-format printer in which an FFC cable having a large wiring length is used, the acquisition accuracy of the temperature information of the pressure chamber input to the control circuit is improved, and the stability of an operation 10 of the control circuit based on the temperature information is improved.

In the aspect of the liquid ejection apparatus, the liquid ejection apparatus may further include a carriage 15 configured to reciprocate along a scanning axis intersecting a transport direction in which a medium is transported, in which the print head may be mounted on the carriage, and the temperature information detected by the temperature detection portion may be input to the control circuit in a period in which the voltage value of the first drive signal is a constant and the carriage is stopped.

According to this liquid ejection apparatus, the temperature information of the pressure chamber input to the control circuit is detected by the temperature detection portion in the period in which the voltage value of the first drive signal is constant and the carriage is stopped, and thus a probability that noise generated by the movement of the carriage interferes with the temperature information of the pressure chamber is reduced. As a result, the acquisition accuracy of the temperature information of the pressure chamber input to the control circuit is further improved, and the stability of the operation of the control circuit based on the temperature information is further improved.

In the aspect of the liquid ejection apparatus, the temperature information detected by the temperature detection portion may be input to the control circuit after a state in which the voltage value of the first drive signal varies is turned to a state in which the voltage value is constant and then a predetermined period elapses.

According to this liquid ejection apparatus, when a predetermined period elapses after the voltage value of the first drive signal is stabilized, the temperature detection portion detects the temperature information of the pressure chamber input to the control circuit, and thus a probability that electric vibration that may occur when the voltage value of the first drive signal varies interferes with the temperature information is reduced. As a result, the acquisition accuracy of the temperature information of the pressure chamber input to the control circuit is further improved, and the stability of the operation of the control circuit based on the temperature information is further improved.

According to another aspect, there is provided a print head that receives a control signal output by a control circuit and a first drive signal output by a first drive signal output circuit and ejects a liquid, including a piezoelectric element that includes a first electrode, a second electrode, and a piezoelectric body and in which the piezoelectric body is located between the first electrode and the second electrode in a stacking direction in which the first electrode, the second electrode, and the piezoelectric body are stacked, and that is driven by receiving the first drive signal, a vibration plate that is located on one side of the stacking direction with respect to the piezoelectric element and is deformed by driving the piezoelectric element,

a pressure chamber substrate that is located on the one side of the stacking direction with respect to the vibration plate and is provided with a plurality of pressure chambers of which volumes change due to deformation of the vibration plate,

a switch circuit that switches whether or not to supply the first drive signal to the piezoelectric element, a wiring substrate that is provided with the switch circuit, and

a temperature detection portion that is located on the other side of the stacking direction with respect to the vibration plate, is electrically coupled to the wiring substrate, and detects temperature information of the pressure chamber, and

the temperature information detected by the temperature detection portion in a period in which a voltage value of the first drive signal is constant is output.

According to this print head, since the temperature detection portion is provided inside the print head, it is possible to accurately detect the temperature information of the pressure chamber. However, since the temperature detection portion is provided inside the print head, the first drive signal for driving the print head may interfere with the temperature information of the pressure chamber detected by the temperature detection portion. In order to solve such a problem, according to the print head, the temperature detection portion outputs the temperature information of the pressure chamber input to the control circuit in a period in which the voltage value of the first drive signal is constant. Consequently, when the temperature detection portion acquires the temperature information of the pressure chamber input to the control circuit, the probability that the first drive signal interferes with the temperature information of the pressure chamber is reduced.

According to this print head, the temperature information of the pressure chamber input to the control circuit is detected by the temperature detection portion in the period in which a voltage value of the first drive signal is constant. Thus, the vibration plate is not deformed and the internal pressure of the pressure chamber does not change in the period in which the temperature information of the pressure chamber input to the control circuit is detected. As a result, a probability that noise generated by the deformation of the vibration plate is superimposed on the temperature information of the pressure chamber input to the control circuit is reduced, and a probability that the temperature in the pressure chamber rises momentarily due to the change in the internal pressure of the pressure chamber when the temperature information of the pressure chamber input to the control circuit is detected is also reduced. Consequently, the acquisition accuracy of the temperature information of the pressure chamber is improved.

In the aspect of the print head, at least a part of the temperature detection portion may be stacked on the vibration plate.

According to this print head, the temperature detection portion can be disposed closer to the pressure chamber, and the accuracy of detecting the temperature of the pressure chamber in the temperature detection portion is further improved.

In the aspect of the print head, the print head may receive the first drive signal and a second drive signal output by a second drive signal output circuit and eject the liquid, the piezoelectric element may be driven by receiving the first drive signal or the second drive signal, and

the temperature information detected by the temperature detection portion may be output in a period in which the voltage value of the first drive signal is constant and a voltage value of the second drive signal is constant.

According to this print head, even in a configuration in which multi-gradation is realized in a short cycle when the piezoelectric element is driven by receiving a plurality of drive signals, the temperature information of the pressure chamber is detected by the temperature detection portion in the period in which the voltage value of the first drive signal is constant and the voltage value of the second drive signal is constant. Therefore, a probability that the first drive signal and the second drive signal interfere with the temperature information of the pressure chamber is reduced, a probability that noise generated due to deformation of the vibration plate is superimposed is reduced, and the temperature in the pressure chamber rises momentarily due to the change in the internal pressure of the pressure chamber is also reduced. Consequently, the acquisition accuracy of the output temperature information of the pressure chamber is improved.

In the aspect of the print head, the print head may be used for a large-format printer that ejects the liquid on a medium having a short side width or more of A3.

According to this print head, the temperature information of the pressure chamber is detected by the temperature detection portion in the period in which the voltage value of the first drive signal is constant. Therefore, even when overshoot or undershoot occurs in the first drive signal, a probability that the first drive signal and the second drive signal interfere with the temperature information of the pressure chamber is reduced, a probability that noise generated due to deformation of the vibration plate is superimposed is reduced, and the temperature in the pressure chamber rises momentarily due to the change in the internal pressure of the pressure chamber is also reduced. Thus, even when the liquid ejection apparatus for which the print head is used is a large-format printer in which an FFC cable having a large wiring length is used, the acquisition accuracy of the temperature information of the pressure chamber input to the control circuit is improved, and the stability of an operation of the control circuit based on the temperature information is improved.

In the aspect of the print head, the print head may be mounted on a carriage configured to reciprocate along a scanning axis intersecting a transport direction in which a medium is transported, and

the temperature information detected by the temperature detection portion may be output in a period in which the voltage value of the first drive signal is a constant and the carriage is stopped.

According to this print head, the output temperature information of the pressure chamber is detected by the temperature detection portion in the period in which the voltage value of the first drive signal is constant and the carriage is stopped, and thus a probability that noise generated by the movement of the carriage interferes with the temperature information of the pressure chamber is reduced. As a result, the acquisition accuracy of the temperature information of the pressure chamber input to the control circuit is further improved.

In the aspect of the print head, the temperature information detected by the temperature detection portion may be output after a state in which the voltage value of the first drive signal varies is turned

to a state in which the voltage value is constant and then a predetermined period elapses.

According to this print head, when a predetermined period elapses after the voltage value of the input first drive signal is stabilized, the temperature detection portion detects the temperature information of the pressure chamber input to the control circuit. Thus, the probability that the electric vibration that may occur when the voltage value of the first drive signal varies interferes with the temperature information is reduced. As a result, the accuracy of acquiring the output temperature information of the pressure chamber is further improved.

What is claimed is:

1. A liquid ejection apparatus comprising:
a control circuit that outputs a control signal;
a first drive signal output circuit that outputs a first drive signal; and
a print head that receives the control signal and the first drive signal and ejects a liquid, wherein
the print head includes

a piezoelectric element that includes a first electrode, a second electrode, and a piezoelectric body and in which the piezoelectric body is located between the first electrode and the second electrode in a stacking direction in which the first electrode, the second electrode, and the piezoelectric body are stacked, and that is driven by receiving the first drive signal,
a vibration plate that is located on one side of the stacking direction with respect to the piezoelectric element and is deformed by driving the piezoelectric element,

a pressure chamber substrate that is located on the one side of the stacking direction with respect to the vibration plate and is provided with a plurality of pressure chambers of which volumes change due to deformation of the vibration plate,
a switch circuit that switches whether or not to supply the first drive signal to the piezoelectric element,
a wiring substrate that is provided with the switch circuit, and

a temperature detection portion that is located on the other side of the stacking direction with respect to the vibration plate, is electrically coupled to wiring substrate, and detects temperature information of the pressure chamber, and

the temperature information detected by the temperature detection portion in a period in which a voltage value of the first drive signal is constant is input to the control circuit.

2. The liquid ejection apparatus according to claim 1, wherein

at least a part of the temperature detection portion is stacked on the vibration plate.

3. The liquid ejection apparatus according to claim 1, further comprising:

a second drive signal output circuit that outputs a second drive signal, wherein

the print head receives the first drive signal and the second drive signal and ejects the liquid,

the piezoelectric element is driven by receiving the first drive signal or the second drive signal, and the temperature information detected by the temperature detection portion in a period in which the voltage value of the first drive signal is constant and a voltage value of the second drive signal is constant is input to the control circuit.

51

4. The liquid ejection apparatus according to claim 1, wherein

the liquid ejection apparatus is a large-format printer that ejects the liquid onto a medium having a short side width or more of A3.

5. The liquid ejection apparatus according to claim 1, further comprising:

a carriage configured to reciprocate along a scanning axis intersecting a transport direction in which a medium is transported, wherein

the print head is mounted on the carriage, and the temperature information detected by the temperature detection portion in a period in which the voltage value of the first drive signal is a constant and the carriage is stopped is input to the control circuit.

6. The liquid ejection apparatus according to claim 1, wherein

the temperature information detected by the temperature detection portion after a state in which the voltage value of the first drive signal varies is turned to a state in which the voltage value is constant and then a predetermined period elapses is input to the control circuit.

7. A print head that receives a control signal output by a control circuit and a first drive signal output by a first drive signal output circuit and ejects a liquid, the print head comprising:

a piezoelectric element that includes a first electrode, a second electrode, and a piezoelectric body and in which the piezoelectric body is located between the first electrode and the second electrode in a stacking direction in which the first electrode, the second electrode, and the piezoelectric body are stacked, and that is driven by receiving the first drive signal,

a vibration plate that is located on one side of the stacking direction with respect to the piezoelectric element and is deformed by driving the piezoelectric element,

a pressure chamber substrate that is located on the one side of the stacking direction with respect to the vibration plate and is provided with a plurality of pressure chambers of which volumes change due to deformation of the vibration plate,

a switch circuit that switches whether or not to supply the drive signal to the piezoelectric element,

52

a wiring substrate that is provided with the switch circuit, and

a temperature detection portion that is located on the other side of the stacking direction with respect to the vibration plate, is electrically coupled to the wiring substrate, and detects temperature information of the pressure chamber, and

the temperature information detected by the temperature detection portion in a period in which a voltage value of the drive signal is constant is output.

8. The print head according to claim 7, wherein at least a part of the temperature detection portion is stacked on the vibration plate.

9. The print head according to claim 7, wherein the print head receives the first drive signal and a second drive signal output by a second drive signal output circuit and ejects the liquid,

the piezoelectric element is driven by receiving the first drive signal or the second drive signal, and

the temperature information detected by the temperature detection portion in a period in which the voltage value of the first drive signal is constant and a voltage value of the second drive signal is constant is output.

10. The print head according to claim 7, wherein the print head is used for a large-format printer that ejects the liquid on a medium having a short side width or more of A3.

11. The print head according to claim 7, wherein the print head is mounted on a carriage configured to reciprocate along a scanning axis intersecting a transport direction in which a medium is transported, and the temperature information detected by the temperature detection portion in a period in which the voltage value of the first drive signal is a constant and the carriage is stopped is output.

12. The print head according to claim 7, wherein the temperature information detected by the temperature detection portion after a state in which the voltage value of the first drive signal varies is turned to a state in which the voltage value is constant and then a predetermined period elapses is output.
